FIG.10

Diagram illustrating a control circuit (FIG.10) with the following components and connections:

- Power and Initial Conditions:** The circuit starts with a main power line. A switch **1001** is connected in series. A coil **CI025** is connected in parallel. A switch **1041** is connected in parallel with the power line.
- Pulse Generation:** A pulse signal is generated through a switch **1021** and a resistor **1022**.
- Relay R1080:** A relay **R1080** is connected to the power line. Its coil is controlled by a switch **1051**. Its contacts are connected in parallel with the power line and also control a switch **1061**.
- Relay R1060:** A relay **R1060** is controlled by a switch **1061**. Its coil is connected in parallel with the power line. Its contacts are connected in parallel with the power line and also control a switch **1062**.
- Relay R1070:** A relay **R1070** is controlled by a switch **1062**. Its coil is connected in parallel with the power line. Its contacts are connected in parallel with the power line and also control a switch **1072**.
- Relay R1020:** A relay **R1020** is controlled by a switch **1072**. Its coil is connected in parallel with the power line. Its contacts are connected in parallel with the power line and also control a switch **1081**.
- Relay R1030:** A relay **R1030** is controlled by a switch **1081**. Its coil is connected in parallel with the power line. Its contacts are connected in parallel with the power line and also control a switch **1023**.
- Relay R1050:** A relay **R1050** is controlled by a switch **1023**. Its coil is connected in parallel with the power line. Its contacts are connected in parallel with the power line and also control a switch **1044**.
- Relay R1040:** A relay **R1040** is controlled by a switch **1044**. Its coil is connected in parallel with the power line. Its contacts are connected in parallel with the power line and also control a switch **1055**.
- Central Logic:** A central section of the circuit contains the following contacts:
  - 1042**: A normally open contact.
  - 1052**: A normally closed contact.
  - 1043**: A normally open contact.
  - 1053**: A normally closed contact.
  - 1064**: A normally open contact.
 These contacts are interconnected to form a logic loop. A switch **1063** is also present in this section, connected to the power line.
- Switches and Contacts:** The circuit includes several other switches and contacts, such as **1021, 1022, 1041, 1051, 1061, 1062, 1072, 1081, 1023, 1044, 1055**, and **1054**.
- Labels:** The circuit includes labels for **PULSE**, **MARGINAL**, **STOP R1060**, **CONT. R1070**, **RESTART R1050**, and **STOP R1040**.

UNITED STATES PATENT OFFICE

2,359,626

TELEPHONE SYSTEM

Thomas F. Crocker, Chicago, Ill., assignor to
 Automatic Electric Laboratories, Inc., a corporation of Delaware

Application January 18, 1943, Serial No. 472,712

20 Claims. (Cl. 179—27)

The present invention relates to telephone systems and more particularly to such systems comprising a central office provided with switching links and a first operator switchboard, a remote control center provided with a second operator switchboard, and an arrangement whereby the switching links may be selectively controlled from the various operator positions at either one of the two switchboards to set up connections.

It is an object of the present invention to provide in a telephone system of the type noted an improved arrangement for identifying, in conjunction with a controlling operator position at either one of the two switchboards, the particular one of the switching links controlled therefrom.

Another object of the invention is to provide in a telephone system, including a group of switching links selectively controllable from an associated operator position, improved link identity apparatus manually controllable from the operator position.

A further object of the invention is to provide in a telephone system, including a group of switching links which are selectively operable to set up connections, an improved arrangement responsive to the release of a connection for releasing the switching link utilized and for automatically identifying the switching link at an associated operator position.

A further object of the invention is to provide in a telephone system, including a group of switching links and an operator switchboard, an improved arrangement for distributing calling ones of the switching links to idle ones of the operator positions at the switchboard or to an associated call storage unit when all of the operator positions are busy.

Further features of the invention pertain to the particular arrangement of the circuit elements of the system, whereby the above-outlined and additional operating features are attained.

The invention, both as to its organization and method of operation, together with further objects and advantages thereof, will best be understood by reference to the following specification taken in connection with the accompanying drawings, in which Figure 1 illustrates the general arrangement of a telephone system embodying the present invention; Figs. 2 to 12, inclusive, taken together, illustrate the details of a system having incorporated therein the features of the invention as briefly outlined above; and Fig. 13 illustrates the mode of combining Figs. 2 to 12, inclusive, to form a unified system.

Description of the apparatus incorporated in the system

Referring now more particularly to Fig. 1 of the drawings, the telephone system there illustrated comprises a central office 20, a distant exchange 30 and a remote control center 40. The central office 20 and the distant exchange 30 are interconnected by a group of toll lines, including the toll line 202; and the central office 20 and the remote control center 40 are interconnected by a number of transfer trunks, including the transfer trunk 1001. The central office 20 serves a number of local telephone stations, including the telephone station T, and comprises a toll switchboard 600 provided with a number of operator positions, the first operator position 601 being illustrated. Similarly, the remote control center 40 comprises a toll switchboard 900 provided with a number of operator positions, the first operator position 901 being illustrated. More particularly, the toll switchboard 600 and the toll switchboard 900 comprise a corresponding number of paired operator positions interconnected by the transfer trunks mentioned. For example, the first operator position 601 at the toll switchboard 600 corresponds to and is paired with the first operator position 901 at the toll switchboard 900, for a purpose more 30 fully explained hereinafter; and the operator positions mentioned are interconnected by the transfer trunk 1001.

The distant exchange 30 comprises a toll operator position 201 of any suitable type terminating the ends of the toll lines 202 etc. in the group in the distant exchange 30; while the ends of the toll lines 202 etc. in the group are terminated in a group of toll line circuits in the central office 20, the toll line circuits being of any suitable type. Specifically, the toll line 202 is terminated in the central office 20 in a toll line circuit 203. In the central office 20 a telephone line 209 extends to the telephone station T and is provided with a line circuit 210 individual thereto of any suitable type. Also the central office 20 comprises a local switch train, including a number of finder-selector links 215 etc. of any suitable type; idle ones of the finder-selector links are distributed for use by an associated allotter 213 of any suitable type. Also the central office 20 comprises a number of C. L. R. trunk circuits 217 etc. of any suitable type. The finder-selector link 215 has access to the telephone line 209 extending to the line circuit 210 and to an incom-

ing trunk 216 extending to the C. L. R. trunk circuit 217.

Further the central office 20 comprises a toll switch train including a group of 100 toll links 300 etc.; the toll link 300 comprising a link finder 200, a toll selector 400 and an access switch 310. Also a toll link distributor 207 of any suitable type is provided in the central office 20 for distributing idle ones of the toll links 300 in a predetermined order, for a purpose more fully explained herein-after. Also the toll switch train includes a number of toll connectors 410 etc. of any suitable type. The link finder 200 has access to an outgoing trunk 204 extending from the toll line circuit 203 and to an outgoing trunk 218 extending from the C. L. R. trunk circuit 217; the toll selector 400 has access to an incoming trunk 205 extending to the toll line circuit 203 and to an incoming trunk 405 extending to the toll connector 410; while the access switch 310 has access to each of a number of control trunks 602 etc. and also to a call storage unit 700 provided in the central office 20. Finally the toll connector 410 has access to the telephone line 209 extending to the line circuit 210. Further the central office 20 comprises a number of link identity display apparatus 500 etc. and a number of link identity sender apparatus 1000 etc. individually associated with the operator positions 601 etc. at the toll switchboard 600; also the link identity sender apparatus 1000 etc. are individually associated with corresponding ones of the transfer trunks 1001 etc. Similarly, the remote control center 40 comprises a number of link identity display apparatus 800 individually associated with the operator positions 901 etc. at the toll switchboard 900. Also the link identity display apparatus 800 etc. are individually associated with corresponding ones of the transfer trunks 1001 etc.

Accordingly, it will be understood that the access switches 310 etc. of the various toll links 300 etc. have access to the various control trunks 602 etc., as well as to the call storage unit 700 as previously noted. Each control trunk 602 etc. is selectively connectible to the corresponding operator position 601 etc. at the toll switchboard 600 or to the corresponding transfer trunk extending between the central office 20 and the remote control center 40. Thus the control trunk 602 is either connected to the first operator position 601 at the toll switchboard 600 or to the corresponding transfer trunk 1001 extending between the central office 20 and the remote control center 40. The transfer trunks 1001 etc. are individually connected to the corresponding operator positions 901 etc. at the toll switchboard 900 in the remote control center 40.

Preferably, each of the toll links is identical to the toll link 300 which comprises, as shown in Figs. 2 to 4, inclusive, a link finder 200, a toll selector 400 and an access switch 310, as previously noted. The link finder 200 is of the 200-point type and comprises a switch mechanism 220 of the Strowger type, including a first wiper set provided with three wipers 221 to 223, inclusive, a second wiper set provided with three wipers 224 to 226, inclusive, and a vertical control wiper 227. Each of the wiper sets is provided with a semi-cylindrical contact bank including ten vertically spaced-apart levels of contact sets arranged in circumferentially spaced-apart relation; while the vertical control wiper 227 is provided with a contact bank including ten vertically spaced-apart control contacts. Each of the

wiper sets is mounted for both vertical and rotary movements while the vertical control wiper 227 is mounted for only vertical movement. Also the switch mechanism 220 comprises a vertical magnet M228 for driving the wiper sets step by step in the vertical direction away from their normal vertical positions, a rotary magnet M230 for driving the wiper sets step by step in the rotary direction away from their normal rotary positions, and a release magnet M232 for releasing the wiper sets and for causing them to be returned to their normal rotary and vertical positions. Also associated with the switch mechanism 220 are two sets of switch springs S233 and S236 which are actuated by the movement of the wiper sets in the vertical direction away from their normal vertical position. Further the link finder 200 comprises a relay group, including two switch-through relays R240 and R250, a start relay R260, a hold relay R330, a cutoff relay R335, a cut-through relay R340, a control relay R350, a transfer relay R360, a link identity relay R365, a stop relay R370, a cutoff relay R375 and a connect relay R380; and a control network connected and arranged in a manner more fully described hereinafter.

The toll selector 400 is of the Strowger type and is connected and arranged in a substantially conventional manner; while the access switch 310 is of the rotary type, including six wipers 311 to 316, inclusive, provided with individually associated contact banks, and a magnet M317 for driving the wipers noted step by step in the clockwise direction.

The call storage unit 700, shown in Fig. 7, comprises a relay group, including a busy relay R710 and six storage relays R720, R730, R740, R750, R760 and R770, six storage lamps L781 etc., a busy lamp L787; and a control network connected and arranged in a manner more fully described hereinafter.

Preferably, each of the operator positions at the toll switchboard 600 is identical to the first operator position 601 which comprises, as shown in Fig. 6, an operator telephone 681 of any suitable type, a relay group including a transfer relay R620, a cut-off relay R630, a call relay R640 and an answer relay R650, and a register sender 680 of any suitable type. Also the first operator position 601 comprises a line lamp L676; a send pilot lamp L677; and a key set including a transfer key K660, a display release key K661, a split key K662, an error key K663, a link identity key K664, a talk key K665, a hold key K666, a busy key K667, a coin rear key K668, a coin front key K669 and a ring key K670; and a control network connected and arranged in a manner more fully described hereinafter.

Preferably, each of the link identity display apparatus individually associated with the operator positions at the toll switchboard 600 is identical to the link identity display apparatus 500 individually associated with the first operator position 601. The link identity display apparatus 500 comprises, as shown in Fig. 5, a relay group including ten tens relays R530, R535 and R540 etc.; ten slave relays R550, R555, R560 etc. individually corresponding to the tens relays; and ten units relays R510, R515, R520 etc. For example, the tens relays R530, R535 and R540 may comprise the respective first, second and tenth tens relays; while the units relays R510, R515 and R520 may comprise the respective first, second and tenth units relays. Also the link identity display apparatus 500 comprises ten tens lamps,

the #1 tens lamp being illustrated, and ten units lamps, the #1, #2 and #0 units lamps being illustrated; and a control network connected and arranged in a manner more fully explained hereinafter.

At this point it is noted that the central office 20 comprises one hundred toll links which are consecutively numbered from 11 to 60; and that the particular toll link which is utilized in setting up a connection from the first operator position 601 at the toll switchboard 600 may be identified by the link identity display apparatus 500 through the operation of the corresponding tens and units relays therein, causing the illumination of the corresponding tens and units lamps arranged before the associated first operator position 601.

Preferably, each of the link identity sender apparatus individually associated with the operator positions at the toll switchboard 600 and with the transfer trunks is identical to the link identity sender apparatus 1000 individually associated with the first operator position 601 and with the transfer trunk 1001. The link identity sender apparatus 1000 comprises, as shown in Figs. 10 to 12, inclusive, a relay group, including three pulse relays R1010, R1020 and R1030, two stop relays R1040 and R1060, a restart relay R1050, a control relay R1070, a release relay R1080, a transfer relay R1110, ten counting relays R1120, R1130, R1140, R1150, R1160 etc., ten tens relays R1260, R1270, R1280 etc., ten slave relays R1240, R1245, R1250 etc., and ten units relays R1210, R1220, R1230 etc.; and a control network connected and arranged in a manner more fully explained hereinafter. For example, the counting relays R1120, R1130, R1140, R1150 and R1160 may comprise the respective first, second, third, ninth and tenth counting relays; the tens relays R1260, R1270 and R1280 may comprise the respective first, second and tenth tens relays; while the units relays R1210, R1220 and R1230 may comprise the respective first, second and tenth units relays.

At this point it is noted that the particular toll link which is utilized in setting up a connection from the first operator position 901 at the toll switchboard 900 may be identified by the link identity sender apparatus 1000 through the operation of the corresponding tens and units relays therein, causing the link identity sender apparatus 1000 to transmit the corresponding tens and units digits over the transfer trunk 1001.

Preferably, each operator position at the toll switchboard 900 is identical to the first operator position 901; which operator position is identical to the corresponding first operator position 601 at the toll switchboard 600. More particularly, the first operator position 901 comprises, as illustrated in Fig. 9, position equipment etc. which is identical to that provided at the first operator position 601; which position equipment includes the display release key K902, the transfer key K903, the error key K904 and the link identity key K905 illustrated.

Preferably, each of the link identity display apparatus individually associated with the operator positions at the toll switchboard 900 is identical to the link identity display apparatus 800 individually associated with the first operator position 901. The link identity display apparatus 800 comprises, as shown in Figs. 8 and 9, a relay group including a pulse relay R820, a transfer relay R830, ten counting relays R840, R850, R860, R870, R880 etc., a digit relay R910, a first digit

start relay R920, a first digit stop relay R930, a second digit start relay R940, a second digit stop relay R950 and ten tens relays R960, R970, etc. For example, the tens relays R960 and R970 may comprise the respective first and tenth tens relays; while the counting relays R840, R850, R860, R870 and R880 may comprise the respective first, second, third, fourth and tenth counting relays. Also the link identity display apparatus 800 comprises ten tens lamps, the #1 and #0 tens lamps being illustrated, and ten units lamps, the #1, #2, #3, #4 and #0 units lamps being illustrated; and a control network connected and arranged in a manner more fully explained hereinafter.

At this point it is noted that the particular toll link which is utilized in setting up a connection from the first operator position 901 at the toll switchboard 900 may be identified by the link identity display apparatus 800 through the operation of the corresponding tens and counting relays therein, causing the illumination of the corresponding tens and units lamps arranged before the associated first operator position 901.

25 A better understanding of the connection and arrangement of the apparatus incorporated in the system will be facilitated from a consideration of the detailed operation of the various pieces of apparatus incident to the setting up of the various toll and trunk calls, as will appear hereinafter.

Initial operation of a toll link

First assuming that a toll call is initiated at the telephone station T in the central office 20, the subscriber first removes the receiver of the telephone instrument thereat from its associated switchhook, thereby to cause the line circuit 210 terminating the telephone line 209 to operate and control the allotter 213 over the start conductor C212. The allotter 213 is controlled to assign an idle one of the finder-selector links in the local switch train, such, for example, as the finder-selector link 215. The allotter 213 then controls the finder-selector link 215 over the cable 214 in order to cause the finder-selector link 215 to seize the telephone line 209 extending to the line circuit 210 and to return dial tone thereover. The subscriber at the calling telephone station T then dials a digit thereat over the telephone line 209 to the finder-selector link 215, whereupon the finder-selector link 215 operates first to select the group of trunks and then an idle trunk therein extending to the group of C. L. R. trunk circuits. For example, assume that the finder-selector link 215 seizes the trunk 216 extending to the C. L. R. trunk circuit 217. At this time, the C. L. R. trunk circuit 217 is controlled in order to cause ground potential to be applied to the common start conductor C206 extending to the toll link distributor 207.

60 The application of ground potential to the common start conductor C206 causes the toll link distributor 207 to initiate operation of the previously selected idle toll link in the associated group, such, for example, as the toll link 300 illustrated. More particularly, the toll link distributor 207 has selected the cable 270 extending to the idle toll link 300 and applies ground potential to the finder start conductor C271 therein in order to complete an obvious circuit for energizing the winding of the start relay R260 in the link finder 200 of the toll link 300. When thus energized the start relay R260 operates to interrupt, at the contacts 266, a point in a multi-

ple path, including the contacts 237 of the set of switch springs S236, for applying ground potential in the link finder 200 to the all-trunks-busy conductor C277 in the cable 270. Also the start relay R260 completes, at the contacts 265, an obvious path for applying battery potential by way of the vertical magnet M228 to the vertical conductor C276 in the cable 270. The application of battery potential in the link finder 200 to the vertical conductor C276 in the cable 270 causes the toll link distributor 207 to apply ground potential thereto in order to complete an obvious circuit for energizing the vertical magnet M228. When thus energized the vertical magnet M228 operates in order to drive the wiper sets of the switch mechanism 220 one step in the vertical direction away from their normal vertical position and to complete, at the contacts 229, an obvious path for applying ground potential to the interrupter conductor C275 in the cable 270. When the wiper sets of the switch mechanism 220 are driven one step in the vertical direction away from their normal vertical positions the sets of switch springs S233 and S236 are actuated, for a purpose more fully explained herein-after, and the vertical control wiper 227 engages the first contact in the associated contact bank.

The application of ground potential to the interrupter conductor C275 in the cable 270 causes the toll link distributor 207 to interrupt the application of ground potential to the vertical conductor C276, thereby to interrupt the previously traced circuit for energizing the vertical magnet M228, whereby the latter magnet restores in order to interrupt, at the contacts 229, the previously mentioned path for applying ground potential to the interrupter conductor C275 in the cable 270. At this time the vertical control wiper 227 engages the first contact in the associated contact bank, whereby ground potential is applied to the test conductor C273 in the cable 270 in the event the trunk 218 extending from the C. L. R. trunk circuit 217 is terminated by a contact set in the first level of the contact bank associated with the first wiper set of the switch mechanism 220. On the other hand, in the event the trunk 218 is not terminated by a contact set in the first level of the contact bank associated with the first wiper set of the switch mechanism 220, no ground potential appears upon the first contact engaged by the vertical control wiper 227 and, accordingly, ground potential is not applied to the test conductor C273 in the cable 270. In the last-mentioned event, when ground potential is removed from the interrupter conductor C275 in the cable 270, the toll link distributor 207 again operates in order to apply ground potential to the vertical conductor C276 in the cable 270, whereby the vertical magnet M228 is reoperated in order to drive the wiper sets of the switch mechanism 220 an additional step in the vertical direction. Accordingly, the wiper sets of the switch mechanism 220 are driven step by step in the vertical direction by the vertical magnet M228 until the first wiper set is driven to the level of contact sets in the associated contact bank upon which the trunk 218 extending to the calling C. L. R. trunk circuit 217 is terminated; whereupon ground potential is applied by way of the vertical control wiper 227 to the test conductor C273 in the cable 270.

The application of ground potential to the test conductor C273 in the cable 270 causes the toll link distributor 207 to be controlled, whereby

ground potential is removed from the vertical conductor C276 in the cable 270 and is applied to the rotary conductor C272 in the cable 270. The application of ground potential to the rotary conductor C272 in the cable 270 completes an obvious circuit, including the contacts 262, 256 and 246, for energizing the rotary magnet M230, whereby the latter magnet operates in order to drive the wiper sets of the switch mechanism 220 one step in the rotary direction away from their normal rotary position and to complete, at the contacts 231, an obvious alternative path for applying ground potential to the interrupter conductor C275 in the cable 270. The application of ground potential to the interrupter conductor C275 in the cable 270 causes the toll link distributor 207 to be controlled, whereby ground potential is removed from the rotary conductor C272 in the cable 270 in order to interrupt the previously traced circuit for energizing the rotary magnet M230. The rotary magnet M230 then restores, thereby to interrupt, at the contacts 231, the previously mentioned path for applying ground potential to the interrupter conductor C275 in the cable 270. At this time the control wiper 223 of the first wiper set of the switch mechanism 220 tests the first contact set in the previously selected level in order to determine whether the trunk 218 extending to the calling C. L. R. trunk circuit 217 is terminated thereby. In the event the trunk 218 is not terminated by the first contact set in the level mentioned, further operation of the toll link distributor 207 takes place, whereby ground potential is reapplied to the rotary conductor C272 in order to effect reoperation of the rotary magnet M230. Accordingly, the wiper sets of the switch mechanism 220 are driven step by step in the rotary direction by the rotary magnet M230 until the control wiper 223 of the first wiper set tests the contact set terminating the trunk 218 extending from the calling C. L. R. trunk circuit 217; at which time battery potential in the calling C. L. R. trunk circuit 217 is applied by way of the control conductor of the trunk 218 to the test wiper 223. Also, at this time, ground potential is applied to the vertical control wiper 227, whereby an obvious circuit, including the contacts 254, is completed for energizing the lower winding of the switch-through relay R240 in order to cause the latter relay to operate. Upon operating, the switch-through relay R240 interrupts, at the contacts 246, a further point in the previously traced circuit for energizing the rotary magnet M230, and completes, at the contacts 245, a holding circuit, including the contacts 261, for energizing the upper winding of the switch-through relay R240 in series with the rotary magnet M230. When this series circuit is completed the switch-through relay R240 is retained in its operated position; however, the rotary magnet M230 does not operate due to the high series resistance of the upper winding of the switch-through relay R240.

Also the switch-through relay R240 completes, at the contacts 243, an obvious connection between the winding of the hold relay R330 and the control wiper 223 of the first wiper set of the switch mechanism 220, whereby the winding of the hold relay R330 is energized in multiple with the lower winding of the switch-through relay R240 and in series with the equipment in the C. L. R. trunk circuit 217, whereby the hold relay R330 operates and the equipment in the C. L. R. trunk circuit 217 is operated to its seizure.

position. Further the switch-through relay R240 completes, at the contacts 241 and 242, an obvious connection, including the contacts 336, 337, 376 and 377, between the line wipers 221 and 222 of the first wiper set of the switch mechanism 220 and the line conductors C401 and C402 extending to the toll selector 400, and interrupts, at the contacts 244, a point in a test circuit traced hereinafter for energizing the upper winding of the switch-through relay R250, thereby positively to prevent operation of the latter relay at this time. Further the switch-through relay R240 completes, at the contacts 248, a circuit, including the contacts 359, 372, 387 and 318, for energizing the magnet M317 of the access switch 310, thereby to initiate operation of the latter switch for a purpose more fully explained hereinafter. Finally the switch-through relay R240 completes, at the contacts 247, an obvious connection, including the contacts 256, 262 and 263, between the rotary conductor C272 and the guard conductor C274 in the cable 270. When the rotary conductor C272 and the guard conductor C274 are thus connected together the toll link distributor 207 is released, whereby the previously traced circuit for energizing the winding of the start relay R260 is interrupted in order to cause the latter relay to restore shortly thereafter, the start relay R260 being of the slow-to-release type. Upon restoring, the start relay R260 interrupts, at the contacts 261, a point in the previously traced holding circuit for energizing the upper winding of the switch-through relay R240 in series with the rotary magnet M230. However, an alternative holding circuit substantially identical to that previously traced has been completed at this time, at the contacts 331, incident to the operation of the hold relay R330. Accordingly, the switch-through relay R240 remains in its operated position at this time. Incident to the operation of the equipment in the C. L. R. trunk circuit 217 to its seized position, battery potential therein is removed from the vertical control wiper 227, thereby to interrupt the previously traced original operating circuit for energizing the lower winding of the switch-through relay R240; however, the latter relay remains in its operated position due to the completion of the previously traced holding circuit for energizing the upper winding thereof in series with the rotary magnet M230. Also, upon restoring, the start relay R260 completes, at the contacts 264, an obvious path, including the contacts 235 of the set of switch springs S233, for applying ground potential to the guard conductor C274 in the cable 270, thereby positively to prevent the toll link distributor 207 from selecting the busy toll link 300 at this time. In passing, it is noted that, when the toll link 300 is rendered busy as explained above, ground potential therein is removed from the all-trunks-busy conductor C277. Accordingly, when all of the one hundred toll links are busy, ground potential is completely removed from the all-trunks-busy conductor C277 in the cable 270, whereby the toll link distributor 207 is rendered completely busy.

Accordingly, at this time, the link finder 200 of the toll link 300 has operated to find the trunk 210 extending from the calling C. L. R. trunk circuit 217 and operation of the access switch 310 is initiated, for a purpose more fully explained hereinafter.

Now assuming that a toll call is initiated at the toll operator position 201 in the distant ex-

change 30, the toll operator first selects an idle one of the toll lines, such, for example, as the toll line 202, then connects the position equipment thereto, and then operates the associated position equipment in order to cause ringing current to be projected over the toll line 202 to the terminating toll line circuit 203. The toll line circuit 203 then operates in order to cause ground potential to be applied to the common start conductor C206, whereby operation of the toll link distributor 207 is initiated in order to initiate operation of the previously selected toll link. Again assuming that the toll link distributor 207 has preselected the idle toll link 300 illustrated, operation of the link finder 200 is initiated in the manner previously explained. More particularly, the operation of the link finder 200 under the control of the toll link distributor 207 is the same as that previously described except that in this case it is assumed that the trunk 204 extending from the toll line circuit 203 is terminated in the contact bank associated with the second wiper set of the switch mechanism 220. Accordingly, in this case, when the second wiper set of the switch mechanism 220 engages the contact set in the associated contact bank terminating the trunk 204, battery potential is applied to the control wiper 226 thereof, thereby to complete an obvious circuit, including the contacts 244, for energizing the upper winding of the switch-through relay R250. When thus energized the switch-through relay R250 operates to interrupt, at the contacts 256, a further point in the previously traced circuit for energizing the rotary magnet M230, and completes, at the contacts 255, a holding circuit, including the contacts 261 and 246, for energizing the lower winding thereof in series with the rotary magnet M230. Also the switch-through relay R250 completes, at the contacts 258, an alternative circuit, including the contacts 249, 359, 372, 387 and 318, for energizing the magnet M317 of the access switch 310. Further the switch-through relay R250 completes, at the contacts 251 and 252, an obvious connection, including the contacts 336, 337, 376 and 377, between the line wipers 224 and 225 of the second wiper set and the line conductors C401 and C402 extending to the toll selector 400. The other functions performed incident to the operation of the switch-through relay R250 are identical to those performed incident to the operation of the switch-through relay R240, as previously explained.

Accordingly, at this time, the link finder 200 of the toll link 300 has operated to find the trunk 204 extending from the calling toll line circuit 203 and operation of the access switch 310 is initiated, for a purpose more fully explained hereinafter.

Considering now the operation of the access switch 310, it is noted that this switch operates to seize an idle one of the control trunks 602 etc. or to seize the call storage unit 700 in the event all of the control trunks 602 etc. are busy at this time. As previously noted, the first control trunk 602 is either connected to the first operator position 601 at the toll switchboard 600, in the event the transfer relay R620 occupies its restored position, or is connected to the first transfer trunk 1001, in the event the transfer relay R620 occupies its operated position; while the first transfer trunk 1001 is connected to the first operator position 901 at the toll switchboard 900. Accordingly, in the event the first control trunk 602 is connected to the first operator po-

sition 601 at the toll switchboard 600, it is either marked as idle or as busy, depending upon the respective idle or busy condition of the first operator position 601. On the other hand, in the event the first control trunk 602 is connected to the first transfer trunk 1001, it is either marked as idle or as busy, depending upon the respective idle or busy condition of the first operator position 901 at the toll switchboard 900. Specifically, the first control trunk 602 is respectively marked as idle or as busy by the application of battery potential or ground potential, respectively, to the control conductor C326 thereof. More particularly, either battery potential or ground potential in the first operator position 601 at the toll switchboard 600 is applied to the conductor C657, depending upon the respective idle or busy condition thereof and may be connected by way of the contacts 620 to the control conductor C326 of the first control trunk 602. Similarly, either battery potential or ground potential in the first operator position 901 at the toll switchboard 900 is applied to the conductor C616 of the first transfer trunk 1001, depending upon the respective idle or busy condition thereof, and may be connected by way of the contacts 629 to the control conductor C326 of the first control trunk 602. Accordingly, it will be understood that, when one of the control trunks 602 etc. is idle, the access switch 310 operates to seize the idle control trunk; on the other hand, when all of the control trunks 602 etc. are busy, the access switch 310 operates to seize the call storage unit 700.

Answering a call at the toll switchboard in the central office

It is contemplated that the toll switchboard 600 in the central office 20 will be utilized normally and that the toll switchboard 900 in the remote control center 40 will be utilized under emergency conditions. Accordingly, under normal operating conditions, the various control trunks 602 etc. will be connected to the corresponding operator positions at the toll switchboard 600. Hence, the transfer relay R620 will normally occupy its restored position, whereby the control trunk 602 is directly connected to the first operator position 601 at the toll switchboard 600.

Assuming that the first operator position 601 at the toll switchboard 600 is idle at this time, battery potential is applied by way of the #1 contacts of the busy key K667, the winding of the call relay R640 and the contacts 654 to the conductor C657 and is further connected by way of the contacts 620 of the restored transfer relay R620 to the control conductor C326 of the first control trunk 602. Again assume that the link finder 200 of the toll link 300 has just operated to seize a calling trunk or toll line and that operation of the access switch 310 has been initiated in the manner explained above. Considering the operation of the access switch 310 in greater detail, the magnet M317 operates, thereby to condition the wipers noted thereof to be driven one step in the clockwise direction and to interrupt, at the contacts 318, the previously traced circuit for energizing the magnet M317. The magnet M317 then restores, thereby to drive the wipers noted of the access switch 310 one step in the clockwise direction and to recomplete, at the contacts 318, the previously traced circuit for energizing the magnet M317. Accordingly, the magnet M317 operates intermittently, thereby to drive

the wipers noted of the access switch 310 step by step in the clockwise direction until an idle control trunk is tested. Assuming that the first control trunk 602 is the first idle control trunk tested by the access switch 310, when the control wiper 316 thereof engages the contact in the associated contact bank terminating the control conductor C326 of the first control trunk 602, a circuit, including the conductor C396 and the contacts 386, 358 and 333, is completed for energizing the winding of the stop relay R370 in view of the fact that battery potential appears upon the control conductor C326 of the first control trunk 602. When thus energized the stop relay R370 operates to interrupt, at the contacts 372, a further point in the previously traced circuit for energizing the magnet M317, thereby positively to arrest further operation of the access switch 310, whereby the latter switch has selected the first control trunk 602 and consequently the first operator position 601 at the toll switchboard 600 at this time. It is noted that, during the operation of the access switch 310, as the control wiper 316 thereof engages contacts in the associated contact banks terminating the control conductors of busy control trunks, ground potential is encountered thereby, completing an obvious path, including the conductors C396 and the contacts 386, 358 and 333, for short-circuiting the winding of the stop relay R370.

The above-traced circuit for energizing the winding of the stop relay R370 includes in series the winding of the call relay R640 at the first operator position 601 at the toll switchboard 600, whereby the latter relay is operated. Upon operating, the call relay R640 completes, at the contacts 642, a holding circuit, including the contacts 652, 654 and the #1 contacts of the busy key K667, for energizing the winding thereof, and completes, at the contacts 643, an obvious circuit for illuminating the line lamp L676, thereby to indicate to the operator at the first operator position 601 that a call has been extended thereto and is waiting to be answered. Also the call relay R640 completes, at the contacts 641, an obvious path, including the contacts 622', for applying ground potential to the chain conductor C679, thereby to prepare a point in a chain circuit for energizing the winding of the busy relay R710 in the call storage unit 700. At this point it is noted that the above-mentioned circuit for energizing the winding of the busy relay R710 is completed when all of the control trunks 602 etc. are connected to busy operator positions at the toll switchboards 600 and 900, whereby the latter relay operates for a purpose more fully explained hereinafter. Further the call relay R640 completes, at the contacts 642, an obvious path, including the contacts 652 and 620, for applying ground potential to the control conductor C326 of the first control trunk 602, thereby to mark the latter trunk as busy to the access switches of the other toll links having access thereto.

Also, upon operating, the stop relay R370 in the link finder 200 completes, at the contacts 371, an obvious circuit for energizing the winding of the connect relay R380, thereby to cause the latter relay to operate. Upon operating, the connect relay R380 completes, at the contacts 385, a holding circuit, including the conductor C396, the control wiper 316 of the access switch 310 and the engaged contact in the associated contact bank and the grounded control conductor C326 of the first control trunk 602, for energizing the winding thereof. Also the con-

nect relay **R380** interrupts, at the contacts **386**, the previously traced circuit for energizing the winding of the stop relay **R370**, thereby to cause the latter relay to restore. Also the connect relay **R380** interrupts, at the contacts **381**, a further point in the previously traced circuit for energizing the magnet **M317**, prepares, at the contacts **384**, a circuit traced hereinafter for energizing the winding of the cutoff relay **R375**, and prepares, at the contacts **383**, a circuit traced hereinafter for energizing in series the windings of the cut-through relay **R340** and the cutoff relay **R335**. Further the connect relay **R380** completes, at the contacts **381** and **382**, a connection between the line wipers of the selected wiper set of the switch mechanism **220** and the line conductors **C321** and **C322** of the first control trunk **602**; the last-mentioned connection including the contacts **241**, **242** or **251**, **252** and the contacts **336**, **337**, **376**, **377**, **381** and **382**, the conductors **C391** and **C392** and the wipers **311** and **312** of the access switch **310** and the engaged contacts in the associated contact banks.

When the operator at the first operator position **601** observes the illuminated line lamp **L676**, she answers the call by operating the talk key **K665**, whereby there is completed, at the #1 and #2 contacts thereof, an obvious connection between the operator telephone **681** and the line conductors **C321** and **C322** of the first control trunk **602**; the last-mentioned connection including the contacts **632**, **634**, **622** and **624**; whereby the operator telephone **681** at the first operator position **601** is operatively connected by way of of the previously traced circuit to the selected wiper set of the link finder **200** and consequently to the calling circuit. The calling party advises the operator at the first operator position **601** concerning the extension of the call at this time. Also when the talk key **K665** is operated there is completed, at the #4 contacts thereof, an obvious circuit for energizing the winding of the answer relay **R650**, thereby to cause the latter relay to operate and interrupt, at the contacts **652** and **654**, the previously traced holding circuit for energizing the winding of the call relay **R640**, whereby the latter relay restores. Also the answer relay **R650** completes, at the contacts **653**, an alternative path, including the #3 contacts of the talk key **K665**, the conductor **C657** and the contacts **620**, for applying ground potential to the control conductor **C326** of the first control trunk **602**. Further the answer relay **R650** completes, at the contacts **651**, a point in multiple with the contacts **641**, for applying ground potential by way of the contacts **622** to the chain conductor **C679** for the purpose previously noted. Moreover, the answer relay **R650** completes, at the contacts **655**, an obvious path for applying ground potential to the conductor **C678** extending to the register sender **680**, whereby the register sender **680** is rendered operative to register one or more digits in response to operation of the associated key set. Finally the answer relay **R650** completes, at the contacts **656**, an obvious circuit for illuminating the send pilot lamp **L677**, thereby to indicate to the operator at the first operator position **601** that the register sender **680** has been seized and is in readiness to receive one or more digits. Upon restoring, the call relay **R640** interrupts, at the contacts **643**, the previously mentioned circuit for illuminating the line lamp **L676** indicating that the call has been answered at the first operator position **601**.

After the operator at the first operator position **601** has learned the destination of the call she operates the key set associated with the register sender **680** in order to cause one or more digits to be registered therein. When a digit is registered in the register sender **680** ground potential is returned over the conductor **C675**, thereby to complete an obvious circuit for energizing the winding of the cutoff relay **R630**. 10 When thus energized the cutoff relay **R630** operates shortly thereafter, as the latter relay is of the slow-to-operate type, to interrupt, at the contacts **632** and **634**, the previously traced connection between the operator telephone **681** and the line conductors **C321** and **C322** of the first control trunk **602**. Also the cutoff relay **R630** completes, at the contacts **631** and **633**, obvious connections respectively including the contacts **622** and **624** between the line conductors **C321** and **C322** of the first control trunk **602** and the conductors **C674** and **C673** extending to the register sender **680**; completes, at the contacts **635**, an obvious connection, including the contacts **626**, between the conductor **C323** of the first control trunk **602** and the conductor **C672** extending to the register sender **680**; and completes, at the contacts **636**, a connection, including the contacts **628** and the error key **K663**, between the conductor **C324** of the first control trunk **602** and the conductor **C671** extending to the register sender **680**. At this time high resistance ground potential in the register sender **680** is applied to the conductor **C671**, thereby to complete a circuit, including the contacts **636**, the error key **K663**, the contacts **628**, the conductor **C324** of the first control trunk **602**, the wiper **314** of the access switch **310** and the engaged contact in the associated contact bank, the conductor **C394** and the contacts **383**, for energizing in series 40 the windings of the cut-through relay **R340** and the cutoff relay **R335** in the link finder **200**. When this series circuit is completed the cutoff relay **R335** operates; however, the cut-through relay **R340** does not operate as the latter relay is of the marginal type. Upon operating, the cutoff relay **R335** interrupts, at the contacts **336** and **337**, the previously traced connection between the selected wiper set of the link finder **200** and the line conductors **C401** and **C402** extending to the toll selector **400**, and completes, at the contacts **338**, an obvious path for applying ground potential to the control conductor **C403** extending to the toll selector **400**. The application of ground potential to the control conductor **C403** renders the toll selector **400** operative in response to a digit transmitted thereto. Also, at this time, a loop circuit is completed between the register sender **680** and the toll selector **400**, this loop circuit including the line conductors **C681** and **C402**, the contacts **376**, **377**, **381** and **382**, the conductors **C391** and **C392**, the line wipers **311** and **312** of the access switch **310** and the engaged contacts in the associated contact banks, the line conductors **C321** and **C322** of the first control trunk **602**, the contacts **622**, **624**, **631** and **633**, and the conductors **C674** and **C673** extending to the register sender **680**. 50 The register sender **680** operates at this time in order to interrupt the above-traced loop circuit in accordance with the first digit registered therein, whereby a corresponding number of impulses constituting a digit are transmitted to the toll selector **400** in order to cause corresponding operation thereof. The toll selector **400** responds to the first digit to select a corresponding group

of trunks and then operates automatically to select an idle trunk in the selected group, all in accordance with conventional practice. More particularly, the toll selector 400 may be operated to select a trunk extending to an idle toll line circuit, such, for example, as the toll line 205 extending to the toll line circuit 203 terminating the toll line 202 extending to the toll operator position 201 in the distant exchange 30. On the other hand, the toll selector 400 may be operated to select a trunk extending to an idle toll connector, such, for example, as the trunk 405 extending to the toll connector 410. In the last-mentioned case, further operation of the register sender 680 would proceed, whereby the toll connector 410 is selectively operative to select a telephone line accessible thereto, such, for example, as the telephone line 209, extending to the line circuit 210 and to the telephone station T, all in accordance with conventional practice.

After all of the digits registered in the register sender 680 have been sent therefrom, direct ground potential is applied to the conductor C671, thereby to complete a low resistance circuit identical to that previously traced for energizing in series the windings of the cut-through relay R340 and the cutoff relay R335, whereby the cutoff relay R335 is retained in its operated position and the cut-through relay R340 operates. The cut-through relay R340 operates at this time as it is of the marginal type, as previously noted. Upon operating, the cut-through relay R340 completes, at the contacts 342, an obvious circuit, including the contacts 354, for energizing the upper winding of the control relay R350, and an obvious multiple circuit, including the contacts 354 and 357 and the resistor 343, for energizing the lower winding of the control relay R350. When both the upper and lower windings of the control relay R350 are thus energized the latter relay operates partially, thereby to interrupt, at the contacts 357, the previously traced circuit for energizing the lower winding thereof and to complete, at the contacts 356, an obvious path, including the contacts 248 or 258 and the contacts 254 and 342, for short-circuiting the lower winding thereof, whereby further operation of the control relay R350 is positively prevented at this time. Also the cut-through relay R340 completes, at the contacts 341, an obvious path for applying battery potential by way of the resistor 334 and the contacts 352 to the control conductor C404 extending to the toll selector 400, thereby to cause the toll selector 400 to operate to its switched-through position for communication purposes.

Shortly after the register sender 680 operates to apply direct ground potential to the conductor C671 extending thereto, following the operation of the register sender 680 to transmit the last digit registered therein, the register sender 680 is released, whereby ground potential is removed from the conductors C671 and C675. When ground potential is removed from the conductor C671 the previously traced circuit for energizing in series the windings of the cutoff relay R335 and the cut-through relay R340 is interrupted, thereby to cause these relays to restore. Upon restoring, the cut-through relay R340 interrupts, at the contacts 342, the previously traced path for short-circuiting the lower winding of the control relay R350, whereby an obvious circuit, including the contacts 248 or 258 and the contacts 356, is completed for energizing in series the upper and lower windings of the control relay

5 R350. When thus energized the latter relay operates fully to complete, at the contacts 351, an obvious alternative path for applying ground potential to the control conductor C403 extending to the toll selector 400. Also the control relay 10 R350 interrupts, at the contacts 352, a further point in the previously traced path for applying resistance battery potential to the control conductor C404 extending to the toll selector 400, and completes, at the contacts 353, an obvious connection between the winding of the hold relay R330 and the control conductor C404. Further the control relay R350 prepares, at the contacts 355, a multiple circuit traced hereinafter for energizing the winding of the transfer relay R360 and the upper winding of the identity relay R365. Upon restoring, the cutoff relay R335 completes, at the contacts 336 and 337, the previously traced connection between the selected wiper set of the link finder 200 and the line conductors C401 and C402 extending to the toll selector 400.

When ground potential is removed from the conductor C675 the previously traced circuit for energizing the winding of the cutoff relay R630 is interrupted, thereby to cause the latter relay to restore and interrupt, at the contacts 631, 633, 25 635 and 636, the previously traced connections between the conductors of the first control trunk 602 and the conductors extending to the register sender 680. Also the cutoff relay R630 completes, at the contacts 632 and 634, the previously traced connection between the operator telephone 681 and the link finder 600.

In order to ring the called party the operator at the first operator position 601 operates the ring key K670 to its front position, thereby to complete, at the #8 contacts thereof, an obvious alternative circuit for energizing the winding of the cutoff relay R630 in order to cause the latter relay to reoperate shortly thereafter. Also when the ring key K670 is operated there is prepared, at the #3 contacts thereof, an obvious path for applying resistance ground potential to the conductor C671, thereby to complete the previously traced circuit for energizing in series the windings of the cut-through relay R340 and the cutoff relay R335 when the cutoff relay R630 operates, whereby the cutoff relay R335 operates and the cut-through relay R340 remains in its restored position, the cut-through relay R340 being of the marginal type, as previously noted. Upon operating, the cutoff relay R335 interrupts, at the contacts 336 and 337, the previously mentioned connection between the selected wiper set of the link finder 200 and the line conductors of the toll selector 400. Finally, at the #7 and #4 contacts of the ring key K670, obvious paths are prepared for respectively connecting ground and resistance battery potentials to the respective line conductors C321 and C322 of the first control trunk 602 and consequently to the respective line conductors C401 and C402 extending to the toll selector 400, which paths are completed when the cutoff relay R630 operates. Finally, upon operating, the cutoff relay R630 again interrupts, at the contacts 632 and 634, the previously traced connection to the operator telephone 681 and completes the connections traced above. The application of ground and resistance battery potentials, respectively, to the line conductors C401 and C402 extending to the toll selector 400 causes operation thereof, whereby ringing current is projected over the trunk seized thereby and consequently over the called circuit.

The operator at the first operator position 601 then restores the ring key K670 in order to effect the restoration of the cutoff relay R630 and the cutoff relay R335 and the removal of ground and battery potentials from the line conductors C401 and C402 extending to the toll selector 400, in an obvious manner. Upon restoring, the cutoff relay R335 recompletes, at the contacts 336 and 337, the previously mentioned connection between the link finder 200 and the toll selector 400; and, upon restoring, the cutoff relay R630 recompletes the previously traced connection between the operator telephone 681 and the link finder 200. After the called party answers, a three-way communication connection is completed, including the called party and the operator at the first operator position 601, this connection being established by way of the link finder 200, the toll selector 400 and the access switch 310 of the toll link 300 utilized.

In the event it is necessary to rering the calling circuit, this may be accomplished by the operator at the first operator position 601 merely by operating the ring key K670 to its rear position. When the ring key K670 is thus operated there is prepared, at the #2 contacts thereof, a circuit, including the contacts 635, 626, the conductor C323 of the first control trunk 602, the wiper 313 of the access switch 310 and the engaged contact in the associated contact bank, C393 and the contacts 324, for energizing the winding of the cutoff relay R375; which circuit is completed when the cutoff relay R630 operates. When thus energized the cutoff relay R375 operates to complete, at the contacts 378, an obvious alternative path for applying ground potential to the control conductor C403 extending to the toll selector 400, and to interrupt, at the contacts 376 and 377, the previously traced connection between the link finder 200 and the toll selector 400. Also the ring key K670 completes, at the #5 contacts thereof, an obvious alternative circuit for energizing the winding of the cutoff relay R630 in order to cause the latter relay to operate shortly thereafter. Finally, when the ring key K670 is operated there is completed, at the #6 and #1 contacts thereof, paths substantially identical to those previously traced for applying ground and resistance battery potentials to the respective line conductors C321 and C322 of the first control trunk 602 and consequently by way of the line wipers 311 and 312 of the access switch 310 and the engaged contacts in the associated contact banks, C391, C392 and the contacts 381, 382, 336, 337 and the contacts of the operated switch-through relay R240 or R250 to the line wipers of the selected wiper set of the switch mechanism 220. This application of ground and battery potentials to the line wipers of the selected wiper set of the switch mechanism 220 causes the calling circuit to operate, whereby ringing current is projected to the calling telephone in the central office 20 or to the calling toll operator position 201 in the distant exchange 30.

The operator at the first operator position 601 then restores the ring key K670, thereby to effect the restoration of the cutoff relays R630 and R375 and the interruption of ground and battery potentials to the line wipers of the selected wiper set of the switch mechanism 220. Upon restoring, the cutoff relay R375 again completes, at the contacts 376 and 377, the previously traced connection between the link finder 200 and the toll selector 400.

In the event the operator at the first operator

position 601 desires to split the connection and talk to the called party to the exclusion of the calling party, this may be accomplished merely by operating the split key K662 to its front position, thereby to complete, at the #2 contacts thereof, an obvious path, including the error key K663 and the contacts 628, for applying resistance ground potential to the conductor C324 of the first control trunk 602. This application of resistance ground potential to the conductor C324 of the first control trunk 602 completes the previously traced circuit for energizing in series the windings of the cut-through relay R340 and the cutoff relay R335, whereby the cutoff relay R335 operates and the cut-through relay R340 remains restored as it is of the marginal type. Upon operating, the cutoff relay R335 interrupts, at the contacts 336 and 337, the previously traced connection between the link finder 200 and the toll selector 400, whereby the first operator position 601 is at this time connected only to the toll selector 400 and consequently to the called circuit. Subsequently, the operator at the first operator position 601 restores the split key K662, thereby to effect the restoration of the cutoff relay R335, whereby the link finder 200 is again connected to the toll selector 400 in order to complete the three-way communication connection previously described.

In the event the operator at the first operator position 601 desires to split the connection and talk to the calling party to the exclusion of the called party, this may be accomplished merely by operating the split key K662 to its rear position, thereby to complete, at the #1 contacts thereof, an obvious path, including the contacts 626, for applying ground potential to the conductor C323 of the first control trunk 602. This application of ground potential to the conductor C323 of the first control trunk 602 completes the previously traced circuit for energizing the winding of the cutoff relay R375, thereby to cause the latter relay to operate. Upon operating, the cutoff relay R375 interrupts, at the contacts 376 and 377, the previously traced connection between the link finder 200 and the toll selector 400, whereby the first operator position 601 is at this time connected only to the link finder 200 and consequently to the calling circuit. Subsequently, the operator at the first operator position 601 restores the split key K662, thereby to effect the restoration of the cutoff relay R375, whereby the toll selector 400 is again connected to the link finder 200 in order to complete the three-way communication connection previously described.

In the event the operator at the first operator position 601 desires to hold the connection and free the operator telephone 681, this may be accomplished merely by operating the hold key K666 and restoring the talk key K665. When the hold key K666 is thus operated there is completed, at the #2 contacts thereof, an obvious alternative circuit for energizing the winding of the answer relay R650 in order to retain the latter relay in its operated position. Also when the hold key K666 is operated there is completed, at the #1 contacts thereof, an obvious alternative circuit for energizing the winding of the connect relay R380, thereby to retain the latter relay in its operated position. When the talk key K665 is thus restored there is interrupted, at the #1 and #2 contacts thereof, the previously traced connection between the operator telephone 681 and the toll link 300. Also when the talk key K665 is restored there is interrupted, at the

#4 and #3 contacts thereof, the previously traced original circuits for respectively energizing the windings of the answer relay R650 and the connect relay R380; however, the latter relays remain in their operated positions at this time due to the operated position of the hold key K666. Subsequently, the operator at the first operator position 601 may reenter the connection by again operating the talk key K665 and restoring the hold key K666 in an obvious manner.

In the event the operator at the first operator position 601 makes an error in operating the key set and consequently in registering digits in the register sender 680, she may release the register sender 680 and the toll selector 400 merely by momentarily operating the error key K663. When the error key K663 is thus operated there is interrupted the previously traced circuit for energizing in series the windings of the cut-through relay R340 and the cutoff relay R335, thereby to cause the operated cutoff relay R335 to restore; also battery potential by way of the windings of the cutoff relay R335 and the cut-through relay R340 is removed from the conductor C671 extending to the register sender 680. Upon restoring, the cutoff relay R335 interrupts, at the contacts 338, the previously mentioned path for applying ground potential to the control conductor C403 extending to the toll selector 400, thereby to cause the toll selector 400 to release and effect the release of the toll connector 410 in the event it is partially operated. The removal of battery potential from the conductor C671 extending to the register sender 680 causes the register sender 680 to release. When the error key K663 is then restored the previously traced circuit for energizing in series the windings of the cut-through relay R340 and the cutoff relay R335 is again completed and battery potential is again applied by way of the windings of the cutoff relay R335 and the cut-through relay R340 to the conductor C671 extending to the register sender 680; whereby the cutoff relay R335 again operates and the register sender 680 is again rendered operative to register digits under the control of the associated key set. Upon re-operating, the cutoff relay R335 recompletes, at the contacts 338, the previously mentioned path for applying ground potential to the control conductor C403 extending to the toll selector 400, whereby the toll selector 400 is again rendered responsive to a digit transmitted thereto from the register sender 680.

In the event it should be necessary for the operator to control the collection and refund of coins over the toll link 300, this may be accomplished by selectively operating the coin rear key K668 and the coin front key K669. For example, a coin may be collected over the called circuit by operating the coin front key K669 to its coin collect position, thereby to effect operation of the cutoff relays R630 and R335 in the manner previously explained and to cause ground potential and positive 110 volt potential to be respectively applied to the line conductors C322 and C321 of the first control trunk 602 and consequently to the respective line conductors C402 and C401 extending to the toll selector 400, whereby coin collecting apparatus associated with the called circuit is operated to collect the deposited coin. Subsequently, the coin front key K669 is restored, thereby to effect the restoration of the cutoff relays R630 and R335 and the removal of the potentials mentioned from the line conductors C402 and C401 extending to the toll selector 400.

On the other hand, a coin may be refunded over the called circuit by operating the coin front key K669 to its coin refund position, thereby to effect operation of the cutoff relays R630 and R335 in the manner previously explained and to cause ground potential and negative 110 volt potential to be respectively applied to the line conductors C322 and C321 of the first control trunk 602 and consequently to the respective line conductors C402 and C401 extending to the toll selector 400, whereby coin refunding apparatus associated with the called circuit is operated to refund the deposited coin. Subsequently, the coin front key K669 is restored, thereby to effect the restoration of the cutoff relays R630 and R335 and the removal of the potentials mentioned from the line conductors C402 and C401 extending to the toll selector 400.

Similarly, a coin may be collected over the calling circuit by operating the coin rear key K668 to its coin collect position, thereby to effect operation of the cutoff relays R630 and R375 in the manner previously explained and to cause ground potential and positive 110 volt potential to be respectively applied to the line conductors C322 and C321 of the first control trunk 602 and consequently to the respective line wipers of the selected wiper set of the switch mechanism 220, whereby coin collecting apparatus associated with the calling circuit is operated to collect the deposited coin. Subsequently, the coin rear key K668 is restored, thereby to effect the restoration of the cutoff relays R630 and R375 and the removal of the potentials mentioned from the selected wiper set of the switch mechanism 220. On the other hand, a coin may be refunded over the calling circuit by operating the coin rear key K668 to its coin refund position, thereby to effect operation of the cutoff relays R630 and R375, in the manner previously explained, and to cause ground potential and negative 110 volt potential to be respectively applied to the line conductors C322 and C321 of the first control trunk 602 and consequently to the respective line wipers of the selected wiper set of the switch mechanism 220, whereby coin refunding apparatus associated with the calling circuit is operated to refund the deposited coin. Subsequently, the coin rear key K668 is restored, thereby to effect the restoration of the cutoff relays R630 and R375 and the removal of the potentials mentioned from the selected wiper set of the switch mechanism 220.

After the operator at the first operator position 601 has set up a connection from the calling circuit to the called circuit by way of the toll link 300 and performed the auxiliary functions described above, she identifies the toll link 300 which is being utilized by momentarily operating the link identity key K664. When the link identity key K664 is thus operated an obvious path, including the error key K663 and the contacts 628, is completed for applying direct ground potential to the conductor C324 of the first control trunk 602, thereby to complete the previously traced circuit for energizing in series the windings of the cut-through relay R340 and the cutoff relay R335, whereby both of the relays mentioned operate at this time, as previously explained. Upon operating, the cut-through relay R340 completes, at the contacts 342, the previously mentioned circuit, including the contacts 355 and 361, for energizing in multiple the winding of the transfer relay R360 and the upper winding of the identity relay R365, whereby the identity relay R365 operates immediately and the transfer relay

R360 operates shortly thereafter, the transfer relay R365 being of the combination slow-to-operate and slow-to-release type. Upon operating, the transfer relay R360 completes, at the contacts 363, an obvious holding circuit, including either the contacts 248 or 258, for energizing the winding thereof. Upon operating, the link identity relay R365 completes, at the contacts 366, an obvious holding circuit, including the resistor 368, for energizing the lower winding thereof and an obvious multiple path, including C395 and the wiper 315 of the access switch 310 and the engaged contact in the associated contact bank, for applying ground potential by way of the lower winding thereof to the marking conductor C325, the marking conductor C325 being individual to the toll link 300 and extending to the link identity display apparatus 500 individually associated with the first operator position 601 at the toll switchboard 600. More particularly, the application of ground potential to the marking conductor C325 by way of the lower winding of the link identity relay R365 completes a multiple holding circuit for energizing the lower winding of the link identity relay R365 in the link finder 200 in series with the winding of the first tens relay R530 in the link identity display apparatus 500, in the event the latter apparatus is idle at this time, whereby the link identity relay R365 is retained in its operated position and the first tens relay R530 operates. The above-mentioned circuit extends from ground by way of the lower winding of the link identity relay R365 and the previously traced path to the marking conductor C325 and therefrom by way of the contacts 624', C571, the resistor 574, the winding of R530, the contacts 533, the contacts of the other tens relays R535, etc., and the contacts 531 to resistance battery. Upon operating, the first tens relay R530 completes, at the contacts 532, a holding circuit substantially identical to that previously traced for energizing the winding thereof in series with the lower winding of the identity relay R365 over the marking conductor C325, and interrupts, at the contacts 533, the previously traced original circuit for energizing the winding thereof in series with the lower winding of the link identity relay R365. Also the first tens relay R530 interrupts, at the contacts 531, a common point in the circuits for energizing the windings of the other tens relays R535, etc., thereby positively to prevent operation of any of the other tens relays in the link identity display apparatus 500 at this time. Further, the first tens relay R530 completes, at the contacts 534, an obvious circuit for energizing the winding of the first slave relay R550, thereby to cause the latter relay to operate. Upon operating, the first slave relay R550 completes, at the contacts 551, 552, etc., obvious connections between the windings of the various units relays R510, R515, etc., and the conductors C571, C572, etc. At this time a circuit for energizing the winding of the first units relay R510 is completed, this circuit extending from the grounded marking conductor C325 by way of the contacts 624', C571, the contacts 551, the winding of R510, the contacts 514, the contacts of the other units relay R515, etc., and the contacts 512 to resistance battery. When this circuit is completed the first units relay R510 operates to complete, at the contacts 513, an obvious holding circuit substantially identical to that traced above for energizing the winding thereof and to interrupt, at the contacts 514, the previously traced original circuit for energizing the winding thereof. Also the 75

first units relay R510 interrupts, at the contacts 512, a common point in the circuits for energizing the windings of the other units relays R515, etc., thereby positively to prevent operation of the other units relays at this time. Further the first units relay R510 completes, at the contacts 515, an obvious circuit, including the contacts 554, for illuminating the #1 tens lamp, and completes, at the contacts 516, an obvious circuit for illuminating the #1 units lamp. At this point it is noted that the tens relays R530, R535, etc., are so interlocked that the lowest order of these relays is operated in the event circuits for energizing two or more of these 15 relays are simultaneously completed. Similarly, the units relays R510, R515, etc., are so interlocked that the lowest order of these relays is operated in the event circuits for energizing two or more of these relays are simultaneously completed. Accordingly, the operation of the link identity relay R365 in the link finder 200 is effective to cause operation of the first tens relay R530 and the first units relay R510 in the link identity display apparatus 500, in the event the latter apparatus is idle at this time, and the consequent illumination of the #1 tens lamp and the #1 units lamp in view of the fact that the identification or number of the toll link 300 is #11. The link identity key K664 is operated only momentarily, as previously noted; and when this key is restored the cutoff relay R335 and the cut-through relay R340 restore in an obvious manner. However, the transfer relay R360 and the link identity relay R365 remain 30 operated, as previously noted. The operated link identity relay R365 in the link finder 200 retains operated the first tens relay R530 and the first units relay R510 in the link identity display apparatus 500. The illumination of the #1 tens lamp and the #1 units lamp in the link identity display apparatus 500 individually associated with the first operator position 601 at the toll switchboard 600 indicates to the operator 35 that the #11 toll link, which is the toll link 300 illustrated, is the toll link which is being utilized to set up the present connection between the calling circuit and the called circuit. After the operator at the first operator position 601 has thus identified the toll link 300 as 40 being the link utilized in setting up the present connection between the calling circuit and the called circuit, she momentarily operates the display release key K661, thereby to complete an obvious path, including C682, the contacts 511 and 551, C571 and the contacts 624', for applying direct ground potential to the marking conductor C325, and obvious alternative multiple holding circuits for energizing the windings of the first tens relay R530 and the first units relay 45 R510. The application of ground potential to the marking conductor C325 completes an obvious path substantially identical to that previously traced for short-circuiting the lower winding of the link identity relay R365 in the link finder 200, thereby to cause the latter relay to restore and interrupt, at the contacts 366, the previously traced holding circuit for energizing the lower winding thereof and the previously traced original path for applying ground potential by way of the lower winding thereof to the marking conductor C325. When the display key K661 is then restored the previously mentioned multiple holding circuits for energizing the windings of the first tens relay R530 and the first units 50

relay R510 are interrupted, thereby to cause these relays to restore. Upon restoring, the first units relay R510 interrupts, at the contacts 515, the previously traced circuit for illuminating the #1 tens lamp and interrupts, at the contacts 516, the previously mentioned circuit for illuminating the #1 units lamp. Also the first units relay R510 reprepares, at the contacts 512, the common point in the circuits for energizing the windings of the other units relays R515, R520, etc. Upon restoring, the first tens relay R530 interrupts, at the contacts 534, the previously mentioned circuit for energizing the winding of the first slave relay R550, thereby to cause the latter relay to restore. Also the first tens relay R530 reprepares, at the contacts 531, the common point in the circuits for energizing the windings of the other tens relays R535, R540, etc. Upon restoring, the first slave relay R550 interrupts, at the contacts 551, etc., the previously traced connections between the units relays R510, etc., and the corresponding marking conductors C325, etc.

After the operator at the first operator position 601 has thus identified the toll link 300 as being the toll link utilized in setting up the present connection between the calling circuit and the called circuit, she restores the talk key K665, thereby to interrupt, at the #4 contacts thereof, the previously mentioned circuit for energizing the winding of the answer relay R650, whereupon the latter relay restores shortly thereafter, the answer relay R650 being of the slow-to-release type. Also, when the talk key K665 is restored there is interrupted, at the #3 contacts thereof, the previously traced path for applying ground potential to the control conductor C326 of the first control trunk 602, thereby to interrupt the previously traced holding circuit for energizing the winding of the connect relay R380 in the link finder 200, whereupon the latter relay restores. Upon restoring, the answer relay R650 recompletes, at the contacts 654, the previously traced path for applying battery potential by way of the winding of the call relay R640 to the control conductor C326 of the first control trunk 602, thereby to mark the first operator position 601 at the toll switchboard 600 as idle to the access switches of the various toll links having access thereto. Also the answer relay R650 interrupts, at the contacts 655, the previously mentioned path for applying ground potential to the conductor C678 extending to the register sender 680, thereby to condition the register sender 680 to be seized again when the next call is routed to the first operator position 601 to be answered. Further the answer relay R650 interrupts, at the contacts 651, the previously mentioned path for applying ground potential to the chain conductor C679, thereby to interrupt a further point in the previously mentioned circuit for energizing the winding of the busy relay R710 in the call storage unit 700. At this time the first operator position 601 at the toll switchboard 600 is completely released and is marked as idle by the application of battery potential to the control conductor C326 of the first control trunk 602 connected thereto, whereby the access switch of a calling one of the toll links may seize the first control trunk 602 in order to route another call to the first operator position 601 to be answered in the manner explained above.

At this point it is noted that the operator at the first operator position 601 at the toll switchboard 600 may render the associated position busy

merely by operating the busy key K667, thereby to interrupt, at the #1 contacts thereof, the previously traced path for applying battery potential by way of the winding of the call relay R640 to the control conductor C326 and to complete, at the #2 contacts thereof, an obvious alternative path for applying ground potential by way of the winding of the call relay R640 to the control conductor C326 of the first control trunk 602. Also when the busy key K667 is thus operated there is completed, at the #2 and #3 contacts thereof, an obvious path, including the contacts 622', for applying ground potential to the chain conductor C679, thereby to prepare a point in the previously mentioned circuit for energizing the winding of the busy relay R710 in the call storage unit 700. Subsequently, when the busy key K667 is restored the first operator position 601 at the toll switchboard 600 is again prepared for use and the first control trunk 602 connected thereto is again marked as idle to the access switches of the toll links having access thereto.

Upon restoring, the connect relay R380 in the link finder 200 interrupts, at the contacts 385, a further point in the previously traced holding circuit for energizing the winding thereof, interrupts, at the contacts 383, a further point in the previously traced circuit for energizing in series the windings of the cut-through relay R340 and the cutoff relay R335, and interrupts, at the contacts 384, a further point in the previously traced circuit for energizing the winding of the cutoff relay R315. Further the connect relay R380 interrupts, at the contacts 381 and 382, the previously traced connection between the link finder 200 and the line wipers 311 and 312 of the access switch 310 and consequently the previously traced connection to the line conductors C321 and C322 of the first control trunk 602. Accordingly, at this time, the established connection between the calling circuit and the called circuit is routed by way of the link finder 200 and the toll selector 400 of the toll link 300 and the link finder 200; and the toll selector 400 are connected together and disconnected from the access switch 310 and consequently from the first operator position 601 at the toll switchboard 600. Hence, the established connection between the calling circuit and the called circuit is routed via the toll link 300 independently of the first operator position 601 at the toll switchboard 600.

Releasing a connection at the toll switchboard in the central office

Again assuming that a connection has been set up from a calling circuit to a called circuit by way of the toll link 300 by the operator at the first operator position 601 at the toll switchboard 600, in the manner explained above, the release of the established connection may be initiated either over the calling circuit or the called circuit. For example, the established connection may include the calling C. L. R. trunk circuit 217 and the telephone station T in the central office 20; and the release of the established connection may be first initiated at the calling telephone station T when the subscriber thereat replaces the receiver of the telephone instrument at the telephone station T upon its associated switchhook. When the release is thus initiated at the calling telephone station T the finder-selector link 215 is controlled via the telephone line 209 and the line circuit 210 in order to effect the control of the C. L. R. trunk circuit 217 via the trunk 216, whereby the C. L. R. trunk circuit 217 returns

ground potential over the control conductor of the trunk 218 to the control wiper 223 of the first wiper set of the switch mechanism 220. This application of ground potential to the control wiper 223 of the first wiper set of the switch mechanism 220 completes an obvious path, including the contacts 243, for short-circuiting the winding of the hold relay R330, thereby to cause the latter relay to restore. Upon restoring, the hold relay R330 interrupts, at the contacts 331, the previously traced holding circuit for energizing the upper winding of the switch-through relay R240 in series with the rotary magnet M230, thereby to cause the switch-through relay R240 to restore. Upon restoring, the switch-through relay R240 interrupts, at the contacts 241, 242 and 243, the previously traced connection between the link finder 200 and the trunk 218 extending to the C. L. R. trunk circuit 217, whereby the C. L. R. trunk circuit 217 is released in order to effect the release of the finder-selector link 215 and the line circuit 210. When the C. L. R. trunk circuit 217 is thus released the trunk 216 extending thereto is marked as idle to the finder-selector links 215 etc. having access thereto. Similarly, when the line circuit 210 is thus released the telephone line 209 extending to the telephone station T is marked as idle to the switches in the local switch train having access thereto.

Further the switch-through relay R240 completes, at the contacts 240', a circuit, including the contacts 266, the contacts 238 of the set of switch springs S236 and the contacts 250', for energizing the release magnet M232, thereby to cause the latter magnet to operate and release the wiper sets of the switch mechanism 220, whereby the wiper sets mentioned are returned to their normal rotary and vertical positions. When the wiper sets of the switch mechanism 220 are thus released the sets of switch springs S233 and S236 are actuated. When the set of switch springs S233 is actuated there is interrupted, at the contacts 235 thereof, the previously traced path for applying ground potential to the guard conductor C274 in the cable 270, thereby to mark the toll link 300 as idle to the toll link distributor 207. When the set of switch springs S236 is actuated there is interrupted, at the contacts 238 thereof, the previously traced circuit for energizing the release magnet M232, thereby to cause the latter magnet to restore.

Similarly, the established connection may include the calling toll line circuit 203 and the toll operator position 201 in the distant exchange 30; and the release of the established connection may be first initiated at the calling toll operator position 201 when the operator thereat operates the associated position equipment in order to cause the toll line circuit 203 to be rung off by way of the toll line 202. When the toll line circuit 203 is thus rung off, it operates to return ground potential over the control conductor of the trunk 204 to the control wiper 226 of the second wiper set of the switch mechanism 220. This application of ground potential to the control wiper 226 of the second wiper set of the switch mechanism 220 completes an obvious path, including the contacts 244 and 253, for short-circuiting the winding of the hold relay R330, thereby to cause the latter relay to restore. Upon restoring, the hold relay R330 interrupts, at the contacts 331, the previously traced holding circuit for energizing the lower winding of the switch-through relay R250 in series with the rotary magnet M230, thereby to cause the switch-

through relay R250 to restore. Upon restoring, the switch-through relay R250 interrupts, at the contacts 251, 252 and 253, the previously traced connection between the link finder 200 and the trunk 204 extending to the toll line circuit 203, whereby the toll line circuit 203 is released. When the toll line circuit 203 is thus released the toll line 202 extending to the toll operator position 201 in the distant exchange 30 is rendered idle.

Further the switch-through relay R250 completes, at the contacts 250', the previously traced circuit for energizing the release magnet M232, thereby to cause the latter magnet to operate and effect the release of the wiper sets of the switch mechanism 220, in the manner previously explained.

On the other hand, the release of the established connection may be initiated over the called circuit, whereupon the toll selector 400 is controlled in order to return ground potential over the control conductor C404 thereof. When ground potential is thus returned over the control conductor C404 extending to the toll selector 400 in an obvious path, including the contacts 353, is completed for short-circuiting the winding of the hold relay R330, thereby to cause the latter relay to restore. Upon restoring, the hold relay R330 interrupts, at the contacts 331, the previously traced holding circuit for retaining operated one of the switch-through relays R240 or R250, whereby the operated switch-through relay restores in order to effect the release of the link finder 200 and the consequent release of the calling circuit, all in the manner previously explained.

Continuing now with the release of the toll link 300, it is noted that when the link finder 200 is released the previously traced holding circuit 40 for energizing in series the upper and lower windings of the control relay R350 is interrupted at the contacts 248 or at the contacts 258 of the respective switch-through relays R240 and R250 incident to the restoration of the operated one 45 of these relays, whereupon the control relay R350 restores. Upon restoring, the control relay R350 interrupts, at the contacts 351, the previously mentioned path for applying ground potential to the control conductor C403 extending to the toll selector 400, whereby the toll selector 400 is released in order to effect the release of the toll connector 410 in the event the established connection includes the last-mentioned connector. Also when the link finder 200 is released the 55 previously traced holding circuit for energizing the winding of the transfer relay R360 is interrupted, thereby to cause the latter relay to restore shortly thereafter, the transfer relay R360 being of the combination slow-to-operate and slow-to-release type, as previously noted. Also, upon restoring, the hold relay R330 completes, at the contacts 332, an alternative circuit, including the contacts 362, for energizing the upper winding of the link identity relay R365, thereby 60 to cause the latter relay to operate. Upon operating, the link identity relay R365 completes, at the contacts 366, the previously traced holding circuit, including the resistor 368, for energizing the lower winding thereof and the previously traced multiple path for applying ground potential by way of the lower winding thereof to the conductor C395, and consequently by way of the wiper 315 of the access switch 310 and the engaged contact in the associated contact bank to the marking conductor C325.

The application of ground potential to the marking conductor C325 effects operation of the first tens relay R530 and the consequent operation of the first slave relay R550 and the first units relay R510 in the event the link identity display apparatus individually associated with the first operator position 601 at the toll switchboard 600 is idle at this time, all in the manner previously explained. The operated first tens relay R530 and the operated first units relay R510 effect the illumination of the #1 tens lamp and the #1 units lamp, thereby to indicate to the operator at the first operator position 601 that the established connection set up by way of the #11 toll link, the toll link 300 illustrated, has been released. The operator at the first operator position 601 then notes the time of the release of the toll link 300 and momentarily operates the display release key K661, thereby to effect the release of the link identity display apparatus 500 and the restoration of the link identity relay R365 in the toll link 300, all in the manner previously explained.

When the link identity relay R365 in the link finder 200 operates incident to the initiation of the release of the toll link 300 in the manner explained above, it prepares, at the contacts 367, a circuit for energizing the magnet M317 of the access switch 310. The above-mentioned circuit is completed at the contacts 249 or 259 of the respective switch-through relays R240 and R250 incident to the release of the link finder 200, whereby the magnet M317 is energized and operates to condition the wipers noted of the access switch 310 to be driven an additional step in the clockwise direction. Subsequently, the link identity relay R365 is restored in order to effect the complete release of the link finder 200 incident to the operation of the display release key K661 at the first operator switch 601, as explained above. Upon restoring, the link identity relay R365 interrupts, at the contacts 367, the above-traced circuit for energizing the magnet M317, whereby the latter magnet restores and drives the wipers noted of the access switch 310 an additional step in the clockwise direction to disengage the contacts in the associated contact banks terminating the first control trunk 602. This arrangement facilitates the distribution of calls to the various operator positions at the toll switchboard 600 from the toll link 300. At this time the toll link 300 is completely released and available for further use.

Reconsidering the operation of the link identity display apparatus 500 in conjunction with the toll link 300, in greater detail, it is again noted that after the operator at the first operator position 601 sets up a connection by way of the toll link 300, she momentarily operates the link identity key K664 in order to effect operation of the link identity relay R365 in the toll link 300, whereby the latter relay effects operation of the link identity display apparatus 500 to identify the toll link 300 in the event the latter apparatus is idle at this time, in the manner previously explained. Further it is again noted that when the established connection set up by way of the toll link 300 is released the link identity relay R365 again operates in order to effect reoperation of the link identity display apparatus 500, in the event the latter apparatus is idle at this time, again to identify the toll link 300. Each time the link identity display apparatus 500 operates to identify a link it must be manually released by the operator

at the first operator position 601 by momentarily operating the display release key K661. Accordingly, the operator at the first operator position 601 may ticket a call which is to be timed by obtaining the time when the link identity display apparatus 500 identifies a toll link incident to the setting up of the connection therethrough and again obtaining the time when the link identity display apparatus 500 reidentifies the toll link incident to the release of the connection therethrough as explained above, a suitable toll ticket being made by the operator.

Further it is noted that as the link identity relay in each toll link is operated it completes a holding circuit for energizing the winding thereof, which holding circuit is not interrupted to cause the link identity relay to restore until after this toll link has been operatively associated with the link identity display apparatus 500. More particularly, in the event the link identity relays in two or more links which are operatively connected by way of the associated access switches to the first control trunk 602 and consequently to the first operator position 601 at the toll switchboard 600 are operated simultaneously, each of the link identity relays is retained in its operated position and marks with ground potential the individually associated marking conductor extending to the link identity display apparatus 500. Thus several of the marking conductors C325 etc. individually corresponding to the different toll links may be marked with ground potential simultaneously. The application of ground potential to two or more of the marking conductors C325 etc. is effective to cause operation of the lowest order tens relay R530 etc. and operation of the lowest order units relay R510 etc., whereby the toll link having the lowest identification number is identified by the link identity display apparatus 500. After this operation of the link identity display apparatus 500 the operator at the first operator position 602 momentarily operates the display release key K661, whereby the link identity display apparatus 500 is released and direct ground potential is applied by way of the marking conductor C325 etc. individual to the toll link which has just been displayed in order to effect the release of the link identity relay 500. Moreover, when the display release key K661 is thus operated direct ground potential is applied only to the marking conductor individual to the toll link which has just been displayed in view of the lockout relation between the tens relays R530 etc. and the arrangement of the resistors 574, 575 etc.

For example, assuming that the link identity display apparatus 500 has just operated to identify the toll link 300, when the display release key K661 is operated direct ground potential is applied to the conductor C682 and by way of the contacts 511 and 551 to the conductor C571 and the contacts 624' to the marking conductors C325. This ground potential is also connected by way of the conductor C682, the contacts 511, 551, the resistors 574 and 575, the conductor C572 and the contacts 626' to the adjacent marking conductor illustrated in the same tens group with the marking conductor C325, and via the resistor 575 and other of the resistors 576 etc. to the other eight marking conductors in the group including the marking conductor C325. However, direct ground potential is only applied to the marking conductor C325 in this group, resistance ground potential being applied to the other mark-

ing conductors therein. The application of direct ground potential to the marking conductor C325 in the group mentioned effects the restoration of the operated link identity relay R365 in the individually associated toll link 300; whereas the application of resistance ground potential to the other marking conductors in the group mentioned will not affect the release of the operated corresponding link identity relays in the corresponding toll links. Further it is noted that the ground potential applied to the conductor C682 incident to the operation of the display release key K661 is not applied to the marking conductors in the other groups of marking conductors in view of the fact that the operated tens relay R530 locks out the other tens relays R535 etc., as previously explained. Thus, it will be readily understood that, each time the display release key K661 is operated, only the identity relay in the toll link which is operatively associated with the link identity display apparatus 500 will be restored. Moreover, when the identity relay R365 in the toll link 300 is restored, ground potential therein is removed from the marking conductor C325, whereby the first units relay R510 restores incident to the restoration of the display release key K661. Also at this time the first tens relay R530 restores in the event ground potential is not applied to any of the other nine marking conductors in the group, including the marking conductor C325. At this time the link identity display apparatus 500 may reoperate to display the identification of the next lowest order of identifications of a toll link provided with an operated identity relay, in an obvious manner.

Answering a call at the toll switchboard in the remote control center

When it is desirable to transfer the traffic normally handled at the first operator position 601 at the toll switchboard 600 in the central office 20 to the first operator position 901 at the toll switchboard 900 in the remote control center 40, this may be accomplished by operating the transfer key K660 at the first operator position 601 or by operating the transfer key K903 at the first operator position 901. When the transfer key K660 is thus operated an obvious circuit is completed for energizing the winding of the transfer relay R620 and when the transfer key K903 is thus operated an obvious circuit, including the conductor C617 in the transfer trunk 1001, is completed for energizing the winding of the transfer relay R620. When thus energized the transfer relay R620 operates to interrupt, at the contacts 622, 624, 626, 628 and 620, the normally completed connection between the respective conductors C321, C322, C323, C324 and C326 of the first control trunk 602 and the first operator position 601 at the toll switchboard 600, and to complete, at the contacts 621, 623, 625, 627 and 629, obvious connections between the respective conductors C321, C322, C323, C324 and C326 of the first control trunk 602 and the respective conductors C611, C612, C613, C614 and C616 of the transfer trunk 1001, the conductors mentioned of the transfer trunk 1001 being connected to the position equipment at the first operator position 901 at the toll switchboard 900, as previously explained. Also the transfer relay R620 interrupts, at the contacts 622', a further point in the previously traced path between the first operator position 601 at the toll switchboard 600 and the chain conductor C679, and completes, at the contacts 621', an obvious connection between the

chain conductor C679 and the conductor C615 of the transfer trunk 1001; whereby ground potential in the first operator position 901 at the toll switchboard 900 is applied to the conductor C615 of the transfer trunk 1001 and consequently by way of the contacts 621' to the chain conductor C679 when the first operator position 901 at the toll switchboard 900 is busy. Further the transfer relay R620 interrupts, at the contacts 624', 626', 628' etc., obvious connections between the marking conductors C325 etc. and the conductors C571 etc. extending to the link identity display apparatus 500, and completes, at the contacts 623', 625', 627' etc., obvious connections between the marking conductors C325 etc. and the conductors C561 etc. extending to the link identity sender apparatus 1000.

Accordingly, at this time, the first control trunk 602 is disconnected from the first operator position 601 at the toll switchboard 600 and is connected to the first transfer trunk 1001 and consequently to the first operator position 901 at the toll switchboard 900. Hence, the first control trunk 602 is marked as idle or busy by the application of battery or ground potential to the control conductor C326 thereof to the access switches of the various toll links having access thereto in accordance with the idle or busy condition of the first operator position 901 at the toll switchboard 900. Moreover, the previously traced chain circuit, including the chain conductor C679, is prepared at the first operator position 901 at the toll switchboard 900 for energizing the winding of the busy relay R710 in the call storage unit 700, whereby the circuit for energizing the winding of the last-mentioned relay is completed when all of the operator positions at the toll switchboard 600 and at the toll switchboard 900, to which the various control trunks 602 etc. are connected, are busy, in a manner more fully explained hereinafter. At this point it is noted that the various control trunks 602 etc. may be disconnected from the corresponding operator positions at the toll switchboard 600 and connected via the corresponding transfer trunks to the corresponding operator positions at the toll switchboard 900 individually or as a group. In other words, a transfer relay may be provided in the position equipment at the first operator position 601 at the toll switchboard 600 which is effective individually to transfer the first control trunk 602 from the first operator position 601 at the toll switchboard 600 to the first operator position 901 at the toll switchboard 900. On the other hand, the transfer relay R620 may be effective commonly to transfer each of the control trunks 602 etc. from the corresponding operator positions at the toll switchboard 600 to the corresponding operator positions at the toll switchboard 900.

Assuming that the first operator position 901 at the toll switchboard 900 is idle at this time, battery potential is applied by way of the busy key and the winding of the call relay therein to the conductor C616 of the first transfer trunk 1001 and by way of the contacts 629 of the operated transfer relay R620 to the control conductor C326 of the first control trunk 602. Again assume that the link finder 200 of the toll link 300 has just operated to seize a calling trunk or toll line and that operation of the access switch 310 has been initiated, in the manner previously explained. Assuming that the first control trunk 602 is the first idle control trunk tested by the access switch 310 incident to operation thereof,

the access switch 310 is controlled to seize the first control trunk 602, whereupon the stop relay R370 is operated in order to effect operation of the connect relay R380 in the link finder 200, all in the manner previously explained. Upon operating, the connect relay R380 effects the restoration of the stop relay R370 and completes, at the contacts 381, 382, 383, 384 and 385, obvious connections between the toll link 300 and the corresponding conductors C611, C612, C614, C613 and C616 of the first transfer trunk 1001 connected to the first operator position 901 at the toll switchboard 900. At this time a holding circuit is completed for energizing the winding of the connect relay R380 in the link finder 200 in series with the winding of the call relay in the position equipment at the first operator position 901, this circuit including the contacts 385, C396, the control wiper 316 of the access switch 310 and the engaged contact in the associated contact bank, the control conductor C326 of the first control trunk 602, the contacts 629 and the control conductor C616 of the first transfer trunk 1001. When this circuit is completed the connect relay R380 in the link finder 200 is retained in its operated position and the call relay in the position equipment at the first operator position 901 operates, thereby to indicate to the operator at the first operator position 901 that a call has been extended thereto and is waiting to be answered.

The operator at the first operator position 901 at the toll switchboard 900 answers the call by operating the associated talk key, whereby a communication connection is completed by way of the link finder 200 and the access switch 310 of the toll link 300 and the first transfer trunk 1001 between the calling circuit and the first operator position 901. The operator at the first operator position 901 then learns the destination of the call and operates the associated register sender, whereby resistance ground potential is applied in the associated register sender to the conductor C614 of the first transfer trunk 1001 in order to effect the operation of the cutoff relay R335 in the link finder 200; and the impulses of a digit are transmitted from the associated register sender over the conductors C611 and C612 of the first transfer trunk 1001 to the toll selector 400 in order to control operation thereof. More particularly, the register sender associated with the first operator position 901 selectively operates the toll selector 400 and also the toll connector 410, in the event such operation is necessary, in order to extend the connection to the called circuit. Upon the conclusion of the operation of the register sender associated with the first operator position 901, direct ground potential is momentarily applied to the conductor C614 of the first transfer trunk 1001, thereby to effect operation of the cut-through relay R340 and the subsequent restoration of the cutoff relay R335 and the cut-through relay R340 in the link finder 200. The operation and restoration of the cut-through relay R340 effect operation of the control relay R350, as previously explained. The operator at the first operator position 901 then controls the ring key, thereby to effect operation of the cutoff relay R335 and the application of ground and battery potentials to the conductors C611 and C612 of the first transfer trunk 1001 and consequently to the line conductors C401 and C402 extending to the toll selector 400, whereby the toll selector 400 operates in order to cause the called circuit to be rung. After the called circuit answers, an obvious three-way communica-

tion connection, including the toll link 300 and the first transfer trunk 1001, is completed, which includes the calling circuit, the called circuit and the first operator position 901 at the toll switchboard 900.

At this time the operator at the first operator position 901 may perform any of the auxiliary control functions in conjunction with the established connection, in the manner previously explained. After the operator at the first operator position 901 has set up the connection by way of the toll link 300 in the manner explained above, she momentarily operates the link identity key K905, thereby to cause direct ground potential to be applied by way of the error key K904 to the conductor C614 of the transfer trunk 1001 in order to effect operation and restoration of the cutoff relay R335 and the cut-through relay R340 in the link finder 200. This operation of the cut-through relay R340 effects operation of the identity relay R365 immediately and operation of the transfer relay R360 shortly thereafter, as previously explained. Upon operating, the link identity relay R365 completes, at the contacts 366, the previously mentioned holding circuit, including the resistor 368, for energizing the lower winding thereof and the previously mentioned path for applying ground potential by way of the lower winding thereof to the conductor C395 and consequently by way of the wiper 315 of the access switch 310 and the engaged contacts in the associated contact bank to the marking conductor C325. This application of ground potential to the marking conductor C325 is applied by way of the contacts 623 to the conductor C501 extending to the link identity sender apparatus 1000, thereby to complete an obvious circuit for energizing the winding of the first tens relay R1260 in the event the latter apparatus is idle at this time. Assuming that the link identity sender apparatus 1000 is idle at this time, the application of ground potential to the conductor C501 completes a circuit, including the resistor 1291, the contacts 1264, the contacts of the other tens relay R1270 etc., and the contacts 1262, for energizing the winding of the first tens relay R1260. When thus energized the first tens relay R1260 operates to complete, at the contacts 1263, a holding circuit substantially identical to that previously traced for energizing the winding thereof and to interrupt, at the contacts 1264, a point in the previously traced original circuit for energizing the winding thereof. Also, upon operating, the first tens relay R1260 interrupts, at the contacts 1262, a common point in the circuits for energizing the windings of the other tens relays R1270 etc., thereby positively to prevent operation of the other tens relays at this time. Also the first tens relay R1260 completes, at the contacts 1265, an obvious circuit for energizing the winding of the first slave relay R1240, thereby to cause the latter relay to operate, and completes, at the contacts 1261, a circuit for energizing the winding of the release relay R1080 in the link identity sender apparatus 1000 in series with the digit relay R910 in the link identity display apparatus 800, the link identity display apparatus 800 being individually associated with the first operator position 901 at the toll switchboard 900, as previously noted. The above-mentioned series circuit extends from ground by way of the contacts 1041 and 1061, the winding of R1080, the contacts 1261, the hold conductor C1295 of the first transfer trunk 1001, the contacts 952, and the winding of R910 to battery. When the above-

traced series circuit is completed the digit relay R910 in the link identity display apparatus 800 operates. However, the release relay R1080 in the link identity sender apparatus 1000 does not operate due to the high series resistance of the winding of the digit relay R910, the release relay R1080 being of the marginal type. Upon operating, the digit relay R910 in the link identity display apparatus 800 conditions the latter apparatus to register the first digit of a two-digit number to be transmitted by the link identity sender apparatus 1000 over the first transfer trunk 1001, as explained more fully below.

Upon operating, the first slave relay R1240 completes, at the contacts 1243, a circuit, including the grounded conductor C501, the contacts 1214, the contacts of the other units relays and the contacts 1212, for energizing the winding of the first units relay R1210, thereby to cause the latter relay to operate. Upon operating, the first units relay R1210 completes, at the contacts 1213, an obvious holding circuit substantially identical to that traced above for energizing the winding thereof and interrupts, at the contacts 1214, the previously traced original circuit for energizing the winding thereof. Also the first units relay R1210 interrupts, at the contacts 1212, a common point in the circuits for energizing the windings of the other units relays R1220 etc., thereby positively to prevent operation of the other units relays at this time. Also, upon operating, the first slave relay R1240 completes, at the contacts 1242, an obvious path for applying ground potential to the marking conductor C1217; and, upon operating, the first units relay R1210 completes, at the contacts 1211, an obvious path for applying ground potential to the marking conductor C1216. Further, the units relay R1210 completes, at the contacts 1215, an obvious path, including the contacts 1241, for applying ground potential to the start conductor C1104, thereby to initiate operation of the pulse relays R1010, R1020 and R1030, in a manner more fully explained below.

Accordingly, in the present example, the first tens relay R1260 and the first units relay R1210 are operated in order positively to prevent operation of the other tens relays R1270 etc. and the other units relays R1220 etc., the first tens relay R1260 and the first units relay R1210 being operated in view of the fact that the identification of the toll link 300 connected to the first transfer trunk 1001 is #11, as previously explained. Also the application of ground potential to the marking conductor C1217 by the operated first slave relay R1240 controls the link identity sender apparatus 1000 to send a first digit of one impulse; and the application of ground potential to the marking conductor C1216 by the operated first units relay R1210 controls the link identity sender apparatus 1000 to send a second digit of one impulse.

Considering further the operation of the link identity sender apparatus 1000, the application of ground potential to the start conductor C1104 completes a circuit, including the contacts 1043 and 1011, for energizing the winding of the pulse relay R1030, thereby to cause the latter relay to operate and complete, at the contacts 1031, an obvious circuit for energizing the winding of the pulse relay R1020. When thus energized the pulse relay R1020 operates to complete, at the contacts 1022, an obvious circuit for energizing the winding of the pulse relay R1010, thereby to cause the latter relay to operate. Upon operating, the

75 pulse relay R1010 interrupts, at the contacts 1011, the previously traced circuit for energizing the winding of the pulse relay R1030, thereby to cause the latter relay to restore and effect the restoration of the pulse relay R1020. Upon restoring, the pulse relay R1020 effects restoration of the pulse relay R1010; and, upon restoring, the pulse relay R1010 reprepares, at the contacts 1011, the previously traced circuit for energizing the winding of the pulse relay R1030. Accordingly, the pulse relays R1020, R1030 and R1010 operate through a number of cycles corresponding to the number of impulses of the first digit and until operation thereof is arrested, as explained more fully below. Each time the pulse relay R1020 operates and restores it completes and then interrupts, at the contacts 1021, an obvious path for applying ground potential to the pulse conductor C1025 of the first transfer trunk 1001, thereby to complete an obvious circuit, including the contacts 951, for energizing the winding of the pulse relay R820 in the link identity display apparatus 800 in order to cause the latter relay to operate and then restore, for a purpose more fully explained hereinafter. Also each time the pulse relay R1020 operates and restores it completes and then interrupts, at the contacts 1023 and 1024, obvious paths for respectively applying ground potential to the conductors C1102 and C1103. At this point it is noted that ground potential applied to the start conductor C1104 is normally connected by way of the contacts 1042 to the conductor C1101.

30 The first time ground potential is applied to the conductor C1103 a circuit, including the contacts of the various counting relays R1120 etc. and the contacts 1135 and 1126, is completed for energizing the winding of the first counting relay R1120, thereby to cause the latter relay to operate. Upon operating, the first counting relay R1120 completes, at the contacts 1123, an obvious holding circuit, including the contacts 1131 and 1112 and the grounded conductor C1102, for energizing the winding thereof. The first time ground potential is applied to the conductor C1102 an obvious path, including the contacts 1112 and the grounded conductor C1101, is completed for short-circuiting the upper winding of the transfer relay R1110. Also, upon operating, the first counting relay R1120 prepares, at the contacts 1124, a circuit traced hereinafter for energizing the winding of the second counting relay R1130. The first time ground potential is removed from the conductor C1102 the previously traced holding circuit for energizing the winding of the first counting relay R1120 and the previously traced path for short-circuiting the upper winding of the transfer relay R1110 are interrupted. At this time a holding circuit is completed for energizing the winding of the first counting relay R1120 in series with the upper winding of the transfer relay R1110; this circuit extending from the grounded conductor C1101 by way of the upper winding of R1110, the contacts 1131 and 1123 and the winding of R1120 to battery. When this series holding circuit is completed the first counting relay R1120 is retained in its operated position and the transfer relay R1110 operates. Upon operating, the transfer relay R1110 prepares, at the contacts 1111, a holding circuit for energizing the lower winding thereof and prepares, at the contacts 1113, a further point in the previously mentioned circuit for energizing the winding of the second counting relay R1130.

75 The next time ground potential is applied to

the conductor C1102 the previously mentioned holding circuit, including the contacts 1111, for energizing the lower winding of the transfer relay R1110 is completed. The next time ground potential is applied to the conductor C1103 the 5 previously mentioned circuit, including the contacts 1113 and 1124, is completed for energizing the winding of the second counting relay R1130, thereby to cause the latter relay to operate. Upon operating, the second counting relay R1130 10 completes, at the contacts 1132, an obvious holding circuit, including the contacts 1141 and the grounded conductor C1101, for energizing the winding thereof and interrupts, at the contacts 1131, the previously traced holding circuit for 15 energizing the winding of the first counting relay R1120 in series with the upper winding of the transfer relay R1110. The first counting relay R1120 then restores; however, the transfer relay R1110 is retained in its operated position due to the completed holding circuit for energizing the lower winding thereof. Further the second counting relay R1130 prepares, at the contacts 1134, a point in a circuit for energizing the winding of the third counting relay R1140. When ground potential is next removed from the conductor C1102 the previously traced holding circuit for energizing the lower winding of the transfer relay R1110 is interrupted, thereby to cause the latter relay to restore. Upon restoring, 20 the transfer relay R1110 prepares, at the contacts 1114, a further point in the previously mentioned circuit for energizing the winding of the third counting relay R1140. In view of the foregoing explanation of the mode of operation of the counting relays R1120 and R1130 in conjunction with the transfer relay R1110, it will be understood that the counting relays R1120, R1130 and R1140 are sequentially operated in 25 response to sequential cycles of operation of the pulse relay R1020.

Each time one of the counting relays R1120 etc. is operated a test circuit is prepared for energizing the winding of the stop relay R1040; and, in the present example, when the first counting relay R1120 is operated, the test circuit mentioned is completed due to the application of ground potential to the marking conductor C1217 in view of the operated position of the first slave relay R1240. More particularly, upon operating, the first counting relay R1120 completes, at the contacts 1127, an obvious circuit, including the contacts 1055 and the grounded marking conductor C1217, for energizing the winding of the stop relay R1040, thereby to cause the latter relay to operate. Upon operating, the stop relay R1040 interrupts, at the contacts 1043, the previously traced circuit for energizing the winding of the pulse relay R1030, thereby to cause the latter relay to restore and effect the restoration of the pulse relays R1020 and R1030. Thus, in the present example, the pulse relay R1020 is operated and restored only once, whereby only one impulse is transmitted over the impulse conductor C1025 of the first transfer trunk 1001 to the pulse relay R820 in the link identity display apparatus 800 at this time. Also, upon operating, the stop relay R1040 completes, at the contacts 1044, an obvious path, including the contacts 1055 and 1127, the grounded start conductor C1104 and the grounded marking conductor C1217, for short-circuiting the winding of the restart relay R1050. Also the stop relay R1040 interrupts, at the contacts 1042, the previously traced connection between the grounded

5 start conductor C1104 and the conductor C1101, thereby to insure the restoration of the transfer relay R1110 and the operated one of the counting relays R1120 etc. In the present example, upon restoring, the first counting relay R1120 10 interrupts, at the contacts 1127, the previously traced path for short-circuiting the winding of the restart relay R1050, whereby a holding circuit for energizing the winding thereof in series with the winding of the stop relay R1040 is completed, this series holding circuit including the contacts 1044 and the grounded start conductor C1104. When this series holding circuit is completed the stop relay R1040 is retained in its operated position and the restart relay R1050 operates shortly thereafter the latter relay being of the slow-to-operate type. Finally, the stop relay R1040 interrupts, at the contacts 1041, the previously traced circuit for energizing the winding of the release relay R1080 in the link identity sender apparatus 1000 in series with the winding of the digit relay R910 in the link identity display apparatus 800 in order to effect the restoration of the digit relay R910 at this time.

Upon operating, the restart relay R1050 completes, at the contacts 1051, an alternative circuit for energizing the winding of the release relay R1080 in the link identity sender apparatus 1000 in series with the digit relay R910 in the link identity display apparatus 800 in order to effect reoperation of the digit relay R910 at this time. Further the restart relay R1050 completes, at the contacts 1054, an obvious connection between the grounded start conductor C1104 and the conductor C1101; and prepares, at the contacts 1052, a circuit traced hereinafter for energizing the winding of the stop relay R1060. Further the restart relay R1050 interrupts, at the contacts 1055, a further point in the previously traced original circuit for energizing the winding of the stop relay R1040 and completes, at the contacts 1053, an alternative circuit, including the contacts 1011 and 1064 and the grounded start conductor C1104, for energizing the winding of the pulse relay R1030. When thus energized the pulse relay R1030 reoperates in order to effect further operation of the pulse relays R1020 and R1010 in the manner previously explained. Accordingly, at this time, the pulse relay R1020 reoperates in order to transmit the impulses of a second digit over the impulse conductor C1025 to the pulse relay R820 in the link identity display apparatus 800 and to effect sequential operation of the counting relays R1120 etc. As each of the counting relays R1120 etc. is operated in the manner previously explained, a test circuit is prepared for energizing the winding of the stop relay R1060.

In the present example, when the first counting relay R1120 operates it completes, at the contacts 1121, an obvious circuit, including the contacts 1062 and 1052 and the grounded marking conductor C1216, for energizing the winding of the stop relay R1060 in view of the fact that the first units relay R1210 occupies its operated position at this time. When thus energized the stop relay R1060 operates to interrupt, at the contacts 1064, the previously traced alternative circuit for energizing the winding of the pulse relay R1030, thereby to cause the latter relay to restore and effect the restoration of the pulse relays R1020 and R1010. Also, the stop relay R1060 interrupts, at the contacts 1062, the previously traced original circuit for energizing the winding thereof and completes, at the contacts 1063, an obvious hold-

ing circuit for energizing the winding thereof in series with the winding of the control relay R1070; the last-mentioned circuit including the grounded start conductor C1104. When the winding of the control relay R1070 is thus energized it operates shortly thereafter, the latter relay being of the slow-to-operate type. Also, the stop relay R1060 interrupts, at the contacts 1061, the previously traced alternative circuit for energizing the winding of the release relay R1080 in the link identity sender apparatus 1000 in series with the digit relay R910 in the link identity display apparatus 800 in order to effect restoration of the digit relay R910 at this time.

Upon operating, the control relay R1070 prepares, at the contacts 1071, an alternative circuit for energizing the winding of the release relay R1080 in the link identity sender apparatus 1000. The link identity sender apparatus 1000 has operated at this time to transmit a first digit of one impulse and a second digit of one impulse over the pulse conductor C1025 of the first transfer trunk 1001 to the link identity display apparatus 800 in view of the fact that the first tens relay R1260 and the first units relay R1210 in the link identity sender apparatus 1000 occupy their operated positions, as previously explained.

Considering now the operation of the link identity display apparatus 800 individually associated with the first operator position 901 at the toll switchboard 900, it is noted that the first time the digit relay R910 operates it completes, at the contacts 913, an obvious circuit, including the contacts 935, for energizing the winding of the first digit start relay R920. When thus energized, the first digit start relay R920 operates to complete, at the contacts 924, an obvious holding circuit, including the contacts 972, 962, etc., of the various tens relays R970, R960, etc., for energizing the winding thereof. As previously noted, the pulse relay R820 operates and follows the impulses of the first digit transmitted over the pulse conductor C1025 of the first transfer trunk 1001 from the link identity sender apparatus 1000, thereby to control sequential operation 45 of the counting relays R840 etc. and the transfer relay R830, in an obvious manner.

In the present example, the first digit comprises one impulse, whereby the first counting relay R840 is operated and a holding circuit is completed for energizing the winding of the first counting relay R840 in series with the upper winding of the transfer relay R830 incident to the restoration of the pulse relay R820. The holding circuit mentioned extends from ground by way of the contacts 933 and 923, the upper winding of R830, the contacts 853 and 843, and the winding of R840 to battery. At the conclusion of the first digit the digit relay R910 restores, as previously explained, thereby to complete, at the contacts 912, a circuit, including the contacts 932, 922 and 842, for energizing the winding of the first tens relay R960. When thus energized the first tens relay R960 operates to complete, at the contacts 961, an obvious holding circuit, including the #2 contacts of the release key K902, for energizing the winding thereof. Also the first tens relay R960 interrupts, at the contacts 962, the previously traced holding circuit for energizing the winding of the first digit start relay R920 and consequently a normally completed path, including the contacts 972 etc. of the various tens relays R970 etc. and the #2 contacts of the display release key K902, for short-circuiting the winding of the first digit stop re-

lay R930. At this time a series holding circuit is completed for energizing the windings of the first digit start relay R920 and the first digit stop relay R930, this circuit including the contacts 924 and the #2 contacts of the display release key K902. When this holding circuit is completed the first digit start relay R920 is retained in its operated position and the first digit stop relay R930 operates. Upon operating, the first digit stop relay R930 interrupts, at the contacts 932, the previously traced original circuit for energizing the winding of the first tens relay R960; and interrupts, at the contacts 933, the previously traced holding circuit for energizing the upper winding of the transfer relay R830 in series with the winding of the first counting relay R840, thereby to cause these relays to restore.

At the beginning of the second digit the digit relay R910 reoperates, thereby to complete, at the contacts 913, a circuit, including the contacts 936, for energizing the winding of the second digit start relay R940. When thus energized the second digit start relay R940 operates to complete, at the contacts 943, a path, including the contacts 913 and 936 and the #2 contacts of the display release key K902, for short-circuiting the winding of the second digit stop relay R950, and to prepare, at the contacts 942, an alternative circuit, including the contacts 934 and 923, for energizing the winding of an operated one of the counting relays R840 etc.

The pulse relay R820 then reoperates and follows the impulses of the second digit transmitted over the pulse conductor C1025 of the first transfer trunk 1001 from the link identity sender apparatus 1000, thereby to control sequential re-operation of the counting relays R840 etc. and the transfer relay R830, in an obvious manner. In the present example, the second digit comprises one impulse, whereby the first counting relay R840 is operated and a holding circuit is completed for energizing the winding of the first counting relay R840 in series with the upper winding of the transfer relay R830 incident to the restoration of the pulse relay R820. The holding circuit mentioned extends from ground by way of the contacts 942, 934 and 923, the upper winding of R830, the contacts 853 and 843, and the winding of R840 to battery. At the conclusion of the second digit the digit relay R910 again restores, as previously explained, thereby to interrupt, at the contacts 913, the previously traced path for short-circuiting the winding of the second digit stop relay R950, whereby a series holding circuit, including the contacts 943 and #2 contacts of the display release key K902, is completed for energizing the windings of the second digit start relay R940 and the second digit stop relay R950. When this series holding circuit is completed the second digit start relay R940 is retained in its operated position and the second digit stop relay R950 operates. Upon operating, the second digit stop relay R950 interrupts, at the contacts 952, a further point in the previously traced circuit for energizing the winding of the digit relay R910 in the link identity display apparatus 800 in series with the release relay R1080 in the link identity sender apparatus 1000, thereby positively to prevent reoperation of the digit relay R910. Further the second digit stop relay R950 interrupts, at the contacts 951, a further point in the previously traced circuit for energizing the winding of the pulse relay R820 in the link identity display apparatus 800, thereby positively to prevent further operation of the

latter relay under the control of the pulse relay R1020 in the link identity sender apparatus 1000.

Also, upon operating, the second digit stop relay R950 completes, at the contacts 954, a circuit, including the contacts 963, for illuminating the #1 tens lamp and completes, at the contacts 953, a circuit, including the contacts 941, 931, 921, 911 and 841, for illuminating the #1 units lamp. In the present example, the #1 tens lamp and the #1 units lamp are illuminated in view of the operated positions of the first tens relay R960 and the first counting relay R840; the first tens relay R960 and the first counting relay R840 occupying their operated positions in view of the fact that both the first and second digits received over the pulse conductor C1025 of the transfer trunk 1001 from the link identity sender apparatus 1000 comprised one impulse.

Accordingly, in the present example, the #1 tens lamp and the #1 units lamp are illuminated, thereby to indicate to the operator at the first operator position 901 at the toll switchboard 900 that the connection set up between the calling circuit and the called circuit, and including the first operator position 901 and the first transfer trunk 1001, utilizes the toll link 300 having the identification #11.

After the operator at the first operator position 901 has thus identified the toll link 300 utilized by momentary operation of the link identity key K905 in the manner explained above, she momentarily operates the display release key K902. When the display release key K902 is thus operated there is interrupted, at the #2 contacts thereof, the previously traced holding circuit for energizing the winding of the first digit start relay R920 in series with the winding of the first digit stop relay R930, the previously traced holding circuit for energizing the winding of the second digit start relay R940 in series with the winding of the second digit stop relay R950, and the previously traced holding circuit for energizing the winding of the first tens relay R960, thereby to cause the relays mentioned to restore. Upon restoring, the first digit start relay R920 interrupts, at the contacts 923, the previously traced holding circuit for energizing the winding of the first counting relay R840 in series with the upper winding of the transfer relay R830, thereby to cause these relays to restore. Upon restoring, the second digit stop relay R950 interrupts, at the contacts 954, the previously traced circuit for illuminating the #1 tens lamp and interrupts, at the contacts 953, the previously traced circuit for illuminating the #1 units lamp. At this time the link identity display apparatus 800 is completely released.

Also when the display release key K902 is momentarily operated there is completed, at the #1 contacts thereof, an obvious path for connecting low resistance battery potential to the hold conductor C1295 of the first transfer trunk 1001, thereby to complete a circuit, including the contacts 1261 and 1071, for energizing the winding of the release relay R1080 in the link identity sender apparatus 1000, whereby the latter relay operates and then restores, the release relay R1080 being of the marginal type as previously noted. Upon operating, the release relay R1080 completes, at the contacts 1081, a path, including the contacts 1072, 1122 and 1243, for applying ground potential to the conductor C501 and by way of the contacts 623' to the marking conductor C325. This application of ground potential to the marking conductor C325 completes the pre-

viously traced path for short-circuiting the lower winding of the link identity relay R365 in the link finder 200 in order to cause the latter relay to restore, whereby ground potential in the link finder 200 is removed from the marking conductor C325 and consequently from the conductor C501. Also, upon operating, the release relay R1080 completes, at the contacts 1081, an alternative holding circuit, including the contacts 1072, 1122 and 1213, for energizing the winding of the first units relay R1210, and a multiple alternative holding circuit, including the contacts 1072, 1122, 1243 and 1263 and the resistor 1291, for energizing the winding of the first tens relay R1260. Subsequently, when the release relay R1080 restores it interrupts, at the contacts 1081, the previously traced alternative holding circuits for energizing in multiple the windings of the first units relay R1210 and the first tens relay R1260, thereby to cause the first units relay R1210 to restore and to effect the restoration of the first tens relay R1260 in the event no ground potential is applied to any of the other conductors in the group, including the conductor C501.

The operator at the first operator position 901 at the toll switchboard 900 then restores the talk key, thereby to effect the release of the connect relay R380 in the link finder 200, whereby the established connection is completed between the calling circuit and the called circuit independently of the first transfer trunk 1001 and the first operator position 901.

Releasing a connection at the toll switchboard in the remote control center

Subsequently, when the release of the established connection, including the toll link 300, is initiated in the manner previously explained, the hold relay R330 in the link finder 200 is restored in order to effect the release of the link finder 200, the restoration of the control relay R350 and the transfer relay R360 and the reoperation of the link identity relay R365, all in the manner previously explained. Upon reoperating, the link identity relay R365 completes, at the contacts 366, the previously traced holding circuit, including the resistor 368, for energizing the lower winding thereof, and completes the previously traced multiple path for applying ground potential to the conductor C395 and consequently to the marking conductor C325 and the connected conductor C501 extending to the link identity sender apparatus 1000. This application of ground potential to the conductor C501 effects reoperation of the first tens relay R1260 and the first units relay R1210 in the event the link identity sender apparatus 1000 is idle at this time, whereby the latter apparatus operates to send a first digit of one impulse and a second digit of one impulse over the pulse conductor C1025 of the first transfer trunk 1001, in the manner previously explained. The two digits of one impulse each transmitted from the link identity sender apparatus 1000 over the pulse conductor C1025 of the first transfer trunk 1001, identifies the toll link 300 as #11, which toll link is utilized in the established connection, the release of which has been initiated.

The link identity display apparatus 800 operates in response to the two digits transmitted thereto over the first transfer trunk 1001 in order to effect the illumination of the #1 tens lamp and the #1 units lamp, in the manner previously explained, in order to indicate to the operator at the first operator position 901 at the toll switchboard 900

that the release of the connection routed by way of the toll link 300, identified by the #11, has been initiated. After the operator at the first operator position has thus identified the toll link 300 she momentarily operates the display release key K902, thereby to effect the release of the link identity display apparatus 800, the release of the link identity sender apparatus 1000 and the restoration of the link identity relay R365 in the link finder 200, all in the manner previously explained. At this time the toll link 300 is completely released and available for further use.

At this point it is noted that the release of the link identity sender apparatus 1000 under the control of the operator at the first operator position 901 at the toll switchboard 900 is essentially the same as the release of the link identity display apparatus 500 under the control of the operator at the first operator position 601 at the toll switchboard 600, whereby only the link identity relay in the link finder of the toll link which has effected operation of the link identity sender apparatus 1000 to send the identification thereof over the first transfer trunk 1001 is restored incident to the operation of the release relay R1080 in the link identity sender apparatus 1000. This result in the link identity sender apparatus 1000 is accomplished by the lockout relation between the various tens relays R1260 etc. and the provision of the various resistors 1291 etc., in a manner similar to that explained in conjunction with the link identity display apparatus 500.

Call storage

When all of the operator positions at the toll switchboards 600 and 900 to which the various control trunks 602 etc. are connected are busy, ground potential appears upon the control conductor of each of the control trunks rendering each of the control trunks nonselectable by the access switches of the various toll selectors. Also, at this time, ground potential either at the first operator position 601 at the toll switchboard 600 or at the first operator position 901 at the toll switchboard 900 is applied to the chain conductor C879, and the chain circuit for energizing the winding of the busy relay R710 in the call storage unit 700 is completed, thereby to cause the latter relay to operate. Upon operating, the busy relay R710 completes, at the contacts 711, an obvious connection between the winding of the first storage relay R720 and the first storage conductor C791 accessible to the access switches of the various toll links.

Now assuming that an idle one of the toll links, such, for example, as the toll link 300, has been assigned for use by the toll link distributor 207 and that the link finder 200 thereof has operated to seize the calling circuit, operation of the access switch 310 of the toll link 300 is initiated. Upon operating, the access switch 310 tests all of the control conductors of the various control trunks 602 etc. as busy by the application of ground potential thereto and tests the second, third, etc., storage conductors C792, C793, etc., as open by the absence of battery potential thereon. Finally, the access switch 310 tests the first storage conductor C791 as prepared by the presence of battery potential via the winding of the first storage relay R720 thereon, whereupon a series circuit is completed for energizing the winding of the stop relay R370 in the link finder 200 and the winding of the first storage relay R720 in the call storage unit 700. This circuit extends from ground by way of the contacts 333, 358, the winding of R370, 75

the contacts 386, C396, the control wiper 316 of the access switch 310 and the engaged contact in the associated contact bank, C791, the contacts 711 and the winding of R720 to battery. When this series circuit is completed the stop relay R370 and the first storage relay R720 operate. Upon operating, the stop relay R370 completes, at the contacts 371, the previously mentioned circuit for energizing the winding of the connect relay R380, thereby to cause the latter relay to operate. Upon operating, the storage relay R720 completes, at the contacts 722, an obvious holding circuit, including the contacts 712, for energizing the winding thereof and an obvious multiple path, including the contacts 712 and 711, for applying ground potential to the first storage conductor C791, thereby to complete an obvious holding circuit, including the contacts 385, C396 and the control wiper 316 of the access switch 310 and the engaged contact in the associated contact bank, for energizing the winding of the connect relay R380. Also, upon operating, the connect relay R380 interrupts, at the contacts 387, a further point in the previously traced circuit for energizing the magnet M317, thereby positively to arrest further operation of the access switch 310 at this time. Further, the connect relay R380 interrupts, at the contacts 386, the previously traced original circuit for energizing the winding of the stop relay R370 in series with the winding of the first storage relay R720, thereby to cause the stop relay R370 to restore.

Also, upon operating, the first storage relay R720 completes, at the contacts 721, an obvious connection for applying battery potential by way of the winding of the second storage relay R730 to the second storage conductor C792, prepares, at the contacts 723, a point in a chain circuit for illuminating the busy lamp L787, and completes, at the contacts 724, an obvious circuit for illuminating the first storage lamp L781. The illumination of the first storage lamp L781 indicates to the operator positions at the toll switchboard 600 that one call is in storage in the call storage unit 700, this call being the call on the toll link 300, as explained above.

Now assuming that another call is initiated at this time, when all of the operator positions at the toll switchboards 600 and 900 to which the control trunks 602 etc. are connected are busy, the toll link distributor 207 will operate to assign another idle one of the toll links and the link finder thereof will operate to seize the calling circuit, whereupon operation of the access switch of the last-mentioned toll link will be initiated. The access switch of the second toll link mentioned which has been taken for use will operate in the previously described manner until the control wiper thereof engages the contact in the associated contact bank terminating the second storage conductor C792, whereupon a series circuit is completed for energizing the winding of the stop relay in the link finder of the second link and the second storage relay R730, thereby to cause operation of the relays mentioned. The operation of the stop relay in the link finder of the second link mentioned causes operation of the connect relay therein and arrests operation of the access switch of the second link. Upon operating, the second storage relay R730 completes, at the contacts 731, an obvious holding circuit, including the contacts 721, for energizing the winding thereof and an obvious multiple path for applying ground potential to the second storage conductor C792, thereby to retain

operated the connect relay in the link finder of the second toll link. Also, the second storage relay R730 prepares, at the contacts 733, a further point in the chain circuit for illuminating the busy lamp L781, completes, at the contacts 734, an obvious circuit for illuminating the second storage lamp L782, and completes, at the contacts 732, an obvious connection for applying battery potential by way of the winding of the third storage relay R740 to the third storage conductor C793. The illumination of the second storage lamp L782 indicates to the operator positions at the toll switchboard 600 that two calls are in storage in the call storage unit 700.

In view of the foregoing explanation of the manner in which the first and second calls initiated at a time when all of the operator positions at the toll switchboards 600 and 900 are busy are stored in the call storage unit 700, it will be understood that the third, fourth, fifth and sixth calls initiated at this time will be stored in a similar manner in the call storage unit 700, causing sequential operation of the third, fourth, fifth and sixth storage relays R740, R750, R760 and R770. Further it will be understood that, upon operating, the storage relays R740, R750, R760 and R770 respectively and sequentially complete the circuits for illuminating the respective call storage lamps indicated. Finally, upon operating, the sixth storage relay R770 completes, at the contacts 771, a path for applying battery potential by way of the resistor 780 to the conservation conductor C797, thereby to cause the access switch of each of the toll links, in addition to the previously mentioned six, to engage the contact in the associated contact bank terminating the conservation conductor C797, whereby the remainder of the calls initiated at this time are conserved until there is storage facility in the call storage unit 700.

In view of the foregoing explanation of the operation of the call storage unit 700, it will be understood that all calls are routed to idle ones of the operator positions at the toll switchboards 600 and 900 when one or more of the operator positions mentioned are idle; when all of the operator positions mentioned are busy the next six calls initiated are stored in order in the respective storage positions in the call storage unit 700; and when all of the storage positions of the call storage unit 700 are occupied, subsequent calls are conserved until there is storage facility in the call storage unit 700.

Continuing now with the operation of the call storage unit 700, it is assumed that one of the operator positions at one of the toll switchboards 600 or 900 becomes idle at this time, whereby the previously traced chain circuit for energizing the winding of the busy relay R710 is interrupted in order to cause the latter relay to restore. Upon restoring, the busy relay R710 interrupts, at the contacts 712, the previously traced multiple holding circuits for energizing the winding of the connect relay R380 in the link finder 200 of the toll link 300 and the winding of the first storage relay R720 in the call storage unit 700, whereby the connect relay R380 restores immediately and the first storage relay R720 restores shortly thereafter, the first storage relay R720 being of the slow-to-release type. Upon restoring, the connect relay R380 recompletes, at the contacts 387, the previously traced circuit for energizing the magnet M317 of the access switch 310, whereby further op-

eration of the latter switch is initiated at this time. Also the connect relay R380 re-prepares, at the contacts 386, the previously traced test circuit including the winding of the stop relay R370 and the control wiper 316 of the access switch 310. More particularly, the access switch 310 operates to seize the control trunk connected to the idle operator position at the toll switchboard 600 or 900, whereby the stop relay R370 operates in order to effect operation of the connect relay R380 and the consequent connection of the toll link 300 to the idle operator position mentioned. At this time the call on the toll link 300 is answered at the operator position mentioned, as previously explained, and the previously traced chain circuit for energizing the winding of the busy relay R710 in the call storage unit 700 is recompleted in order to cause the latter relay to reoperate.

Upon restoring, the first storage relay R720 interrupts, at the contacts 721, the previously traced circuit for energizing the winding of the second storage relay R730, thereby to cause the latter relay to restore shortly thereafter. Upon restoring, the second storage relay R730 interrupts, at the contacts 731, the previously traced path for applying ground potential to the second storage conductor C792 and interrupts, at the contacts 732, the previously traced circuit for energizing the winding of the third storage relay R740, thereby to cause the latter relay to restore shortly thereafter. When ground potential is removed from the second storage conductor C792 incident to the restoration of the second storage relay R730, operation of the access switch of the second link mentioned is initiated, whereby the access switch of the link mentioned operates to cause the control wiper thereof to engage the contact in the associated contact bank terminating the first storage conductor C791, whereby the stop relay in the second toll link mentioned and the first storage relay R720 in the call storage unit 700 reoperate.

Accordingly, the restoration of the first storage relay R720 causes sequential restoration of the second, third etc. storage relays R730, R740 etc., thereby to initiate sequential operations of the access switches of the second, third etc. toll links. Upon reoperating, the first storage relay R720 recompletes, at the contacts 721, the previously traced path for applying battery potential by way of the winding of the second storage relay R730 to the second storage conductor C792, thereby to cause the access switch of the third toll link to be arrested when the control wiper thereof engages the contact terminating the second storage conductor C792 and to cause the second storage relay R730 to reoperate. In view of the above explanation of the restoration and subsequent reoperation of each of the storage relays R720, R730, etc., it will be understood that the first toll link occupying the first storage position in the call storage unit 700 is operated to find the idle operator position at the toll switchboard 600 or 900 while the access switches of the second, third etc. toll links respectively occupying the second, third etc. storage positions in the call storage unit 700 are advanced one position in order respectively to occupy the first, second etc. storage positions in the call storage unit 700.

Further, it is noted that, when the sixth storage relay R770 restores, it interrupts, at the contacts 771, the previously traced path for applying battery potential by way of the resistor 780 to the conservation conductor C797, thereby to cause

the access switches of the seventh, eighth etc. toll links to operate further, whereupon the control wiper of the access switch of one of the seventh, eighth etc. toll links engages the contact in the associated contact bank terminating the sixth storage conductor C796 in order to cause subsequent operation of the access switch of the last-mentioned toll link to be arrested. Accordingly, at this time, the call on the last-mentioned toll link is stored in the sixth position of the call storage unit 700; and the access switches of the remainder of the toll links continue to operate until the wipers thereof reengage the contacts in the associated contact banks terminating the conservation conductor C797, thereby to cause the calls on the remainder of the toll links to be conserved until there is storage facility in the call storage unit 700.

In view of the foregoing explanation of the operation of the call storage unit 700 in order to release calls from storage, it will be understood that the call stored in the first position of the call storage unit 700 is first released and the remainder of the calls stored are advanced one position. Accordingly, calls are stored in the call storage unit 700 when all of the operator positions at the toll switchboards 600 and 900 are busy, in a predetermined order, and are released as the operator positions at the toll switchboards 600 and 900 become idle in the same predetermined order. Furthermore, all incoming calls are conserved to be stored when all of the storage facilities of the call storage unit 700 are utilized and are subsequently advanced to call storage positions indiscriminately. Hence, the call storage unit 700 comprises not only call storage facility but also constitutes a call storage distributor.

Conclusions

From the foregoing it is apparent that a telephone system is provided which comprises a central office including a plurality of switching links and a toll switchboard, and a remote control center including a toll switchboard; which system embodies an improved arrangement, whereby the switching links in the central office may be selectively operated to set up connections under the control of the operator positions at either the toll switchboard in the central office or the toll switchboard in the remote control center and whereby the connections set up by the various switching links may be supervised from the corresponding operator positions at the two toll switchboards.

While one embodiment of the invention has been disclosed, it will be understood that various modifications may be made therein which are within the true spirit and scope of the invention.

What is claimed is:

1. In a telephone system, an exchange including a plurality of lines and a group of links and a first operator switchboard, a remote control center including a second operator switchboard, a control trunk, means for selectively connecting said control trunk to said two operator switchboards, means controllable over said control trunk from the one of said operator switchboards to which said control trunk is connected for operating any one of said links to set up a connection between two of said lines, two apparatus individually associated with said two operator switchboards, and means for operating the one of said apparatus associated with the one of said

operator switchboards to which said control trunk is connected to identify said one link.

2. In a telephone system, an exchange including a plurality of lines and a group of links and a first operator switchboard, a remote control center including a second operator switchboard, a control trunk, means for selectively connecting said control trunk to said two operator switchboards, means controllable over said control trunk from the one of said operator switchboards to which said control trunk is connected for operating any one of said links to set up a connection between two of said lines, two apparatus individually associated with said two operator switchboards, and additional means controllable over said control trunk from the one of said switchboards to which said control trunk is connected for operating the associated one of said apparatus to identify said one link.

3. In a telephone system, a plurality of lines, a group of links, a control trunk, two remotely disposed operator switchboards, means for selectively connecting said control trunk to said two operator switchboards, automatic means for connecting any one of said links to said control trunk, means controllable from the one of said operator positions to which said control trunk is connected for setting up a connection by way of said one link between a calling one of said lines and a called one of said lines, two apparatus individually associated with said two operator switchboards, each of said apparatus being operative when said control trunk is connected to the associated operator switchboard to identify the particular one of said links which is connected to said control trunk, and means for operating the one of said apparatus associated with the one of said operator switchboards to which said control trunk is connected.

4. In a telephone system, a plurality of lines, a group of links, a control trunk, two remotely disposed operator switchboards, means for selectively connecting said control trunk to said two operator switchboards, automatic means for connecting any one of said links to said control trunk, means controllable from the one of said operator positions to which said control trunk is connected for setting up a connection by way of said one link between a calling one of said lines and a called one of said lines, two apparatus individually associated with said two operator switchboards, each of said apparatus being operative when said control trunk is connected to the associated operator switchboard to identify the particular one of said links which is connected to said control trunk, and additional means controllable from the one of said operator positions to which said control trunk is connected for operating the associated one of said apparatus.

5. In a telephone system, a plurality of lines, a group of links, a control trunk, a first operator position, a transfer trunk, a second operator position connected to said transfer trunk, means for selectively connecting said control trunk to said first operator position and to said transfer trunk, automatic means for connecting any one of said links to a calling one of said lines and for connecting said one link to said control trunk, means controllable from said first operator position over said control trunk or from said second operator position over said transfer trunk and said control trunk for connecting said one link to a called one of said lines, means for applying a marking individual to said one link to said

control trunk, first apparatus associated with said first operator position, means controlled in the event said control trunk is connected to said first operator position and governed in accordance with the marking applied thereto for operating said first apparatus to identify the corresponding one of said links which is connected to said control trunk, a sender, means controlled in the event said control trunk is connected to said transfer trunk and governed in accordance with the marking applied thereto for operating said sender to send a corresponding signal over said transfer trunk, second apparatus associated with said second operator position, and means governed in accordance with the signal sent over said transfer trunk for operating said second apparatus to identify the corresponding one of said links which is connected to said control trunk.

6. In a telephone system, a plurality of lines, a group of links, a control trunk, a first operator position, a transfer trunk, a second operator position connected to said transfer trunk, means for selectively connecting said control trunk to said first operator position and to said transfer trunk, automatic means for connecting any one of said links to a calling one of said lines and for connecting said one link to said control trunk, means controllable from said first operator position over said control trunk or from said second operator position over said transfer trunk and said control trunk for connecting said one link to a called one of said lines, additional means controllable from said first operator position over said control trunk or from said second operator position over said transfer trunk and said control trunk for applying a marking individual to said one link to said control trunk, first apparatus associated with said first operator position, means controlled in the event said control trunk is connected to said first operator position and governed in accordance with the marking applied thereto for operating said first apparatus to identify the corresponding one of said links which is connected to said control trunk, a sender, means controlled in the event said control trunk is connected to said transfer trunk and governed in accordance with the marking applied thereto for operating said sender to send a corresponding signal over said transfer trunk, second apparatus associated with said second operator position, and means governed in accordance with the signal sent over said transfer trunk for operating said second apparatus to identify the corresponding one of said links which is connected to said control trunk.

7. In a telephone system, a plurality of lines, a group of links, a control trunk, two remotely disposed operator switchboards, means for selectively connecting said control trunk to said two operator switchboards, means for setting up a connection by way of any one of said links between a calling one of said lines and a called one of said lines, two apparatus individually associated with said two operator switchboards, and means responsive to a control operation performed over the connection set up by way of said one link for operating the one of said apparatus associated with the one of said operator switchboards to which said control trunk is connected to identify said one link.

8. In a telephone system, a plurality of lines, a group of links, a control trunk, a first operator position, a transfer trunk, a second operator position connected to said transfer trunk, means for

selectively connecting said control trunk to said first operator position and to said transfer trunk, means for setting up a connection by way of any one of said links between a calling one of said lines and a called one of said lines, means responsive to a control operation performed over the connection set up by way of said one link for applying a marking individual to said one link to said control trunk, first apparatus associated with said first operator position, means controlled in the event said control trunk is connected to said first operator position and governed in accordance with the marking applied thereto for operating said first apparatus to identify the corresponding one of said links, a sender, means controlled in the event said control trunk is connected to said transfer trunk and governed in accordance with the marking applied thereto for operating said sender to send a corresponding signal over said transfer trunk, second apparatus associated with said second operator position, and means governed in accordance with the signal sent over said transfer trunk for operating said second apparatus to identify the corresponding one of said links.

9. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one link to a called one of said lines, apparatus operative to identify the particular one of said links which is connected to said control trunk, and means including a manually operable identity device at said operator position for operating said apparatus.

10. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one link to a called one of said lines, display apparatus operative to identify the particular one of said links which is connected to said control trunk, means including an identity key at said operator position for operating said display apparatus, and means including a release key at said operator position for releasing said display apparatus.

11. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one link to a called one of said lines, additional means controllable over said control trunk from said operator position for applying a marking individual to said one link to said control trunk, and apparatus operative in accordance with the marking applied to said control trunk for identifying the corresponding one of said links which is connected thereto.

12. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one

link to a called one of said lines, said one link including an identity relay operative to apply a marking individual to said one link to said control trunk, additional means controllable over said control trunk from said operator position for selectively operating and restoring said identity relay, apparatus adapted to be operated in accordance with the marking applied to said control trunk for identifying the corresponding one of said links which is connected thereto, and means responsive to the application of a marking to said control trunk for operating said apparatus and responsive to the removal of a marking from said control trunk for releasing said apparatus.

13. In a telephone system, a plurality of lines, a group of links, each of said links including an answer switch and a call switch, a control trunk, an operator position, automatic means for operating the answer switch of an idle one of said links to seize a calling one of said lines and for connecting said one link to said control trunk, means controllable over said control trunk from said operator position for operating the call switch of said one link to seize a called one of said lines, apparatus operative to identify the particular one of said links which is connected to said control trunk, and additional means controllable over said control trunk from said operator position for completing an operative connection through said one link between the calling and called lines and for operating said apparatus.

14. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one link to a called one of said lines, means for sending a plural digit number individual to said one link over said control trunk, and apparatus responsive to a plural digit number sent over said control trunk for identifying the corresponding one of said links which is connected thereto.

15. In a telephone system, a plurality of lines, a group of links, a control trunk, an operator position, automatic means for connecting an idle one of said links to a calling one of said lines and for connecting said one link to said control trunk, means controllable over said control trunk from said operator position for connecting said one link to a called one of said lines, a sender operative to send a signal individual to said one link over said control trunk, additional means controllable over said control trunk from said operator position for operating said sender, and apparatus responsive to a signal sent over said control trunk for identifying the corresponding one of said links which is connected thereto.

16. In a telephone system, a plurality of lines, a group of links, a control trunk, an operator position, means for operating an idle one of said links to set up a connection between a calling one of said lines and a called one of said lines, apparatus associated with said operator position, and means responsive to the release of said connection for releasing said one link and for con-

trolling the operation of said apparatus over said control trunk to identify said one link.

17. In a telephone system, a plurality of lines, a group of links, a control trunk, an operator position, means for operating an idle one of said links to set up a connection between a calling one of said lines and a called one of said lines, means responsive to the release of said connection for releasing said one link and for applying a marking individual to said one link to said control trunk, apparatus associated with said operator position, and means controlled in accordance with the marking applied to said control trunk for operating said apparatus to identify said one link.

18. In a telephone system, a plurality of lines, a group of links, a control trunk, an operator position, means for operating an idle one of said links to set up a connection between a calling one of said lines and a called one of said lines, a sender, means responsive to the release of said connection for releasing said one link and for controlling said sender over said control trunk to cause it to send a signal individual to said one link, and apparatus associated with said operator position and responsive to the signal sent by said sender for identifying said one link.

19. In a telephone system, a plurality of lines, a group of links, a switchboard including a plurality of operator positions, a call storage unit, automatic means for connecting an idle one of said links to a calling one of said lines and for connecting said one link either to an idle one of said operator positions or to said call storage unit in the event all of said operator positions are busy, means controlled in the event said one link is connected to said call storage unit and in response to one of said operator positions becoming idle for disconnecting said one link from said call storage unit and for connecting it to said one operator position.

20. In a telephone system, a plurality of lines, a group of links, a switchboard including a plurality of operator positions, a call storage unit, automatic means for connecting an idle one of said links to a calling one of said lines and for connecting said one link either to an idle one of said operator positions or to said call storage unit in the event all of said operator positions are busy, means controlled in the event said one link is connected to said call storage unit and in response to one of said operator positions becoming idle for disconnecting said one link from said call storage unit and for connecting it to said one operator position, means controllable from said one operator position for connecting said one link to a called one of said lines, a sender operative to send a signal individual to said one link, additional means controllable from said one operator position for operating said sender, and apparatus responsive to a signal sent from said sender for identifying the corresponding one of said links which is connected to said one operator position.

THOMAS F. CROCKER.
